UNITED STATES PATENT OFFICE.

HIRAM JOSEPH HALLE, OF CLEVELAND, OHIO, ASSIGNOR, BY MESNE ASSIGNMENTS,
TO ELLIOTT-FISHER CO.

CALCULATING ATTACHMENT FOR TYPEWRITING MACHINES.

1,405,209.

Specification of Letters Patent. Patented Jan. 31, 1922.

Application filed October 11, 1902. Serial No. 126,909.

To all whom it may concern:

Be it known that I, HIRAM J. HALLE, citizen of the United States, residing at Cleveland, in the county of Cuyahoga and State of Ohio, have invented a new and useful Calculating Attachment for Typewriting Machines, of which the following is a specification.

This invention relates to a novel calculating machine, and also to a combined calculating and typewriting machine, including the calculating mechanism viewed as a typewriter attachment.

This invention may be considered as an advance in the art exemplified by the invention of Charles F. Laganke and John A. Smith, disclosed in their concurrent application, No. 120,925. Said application discloses a computing device or totalizer, including a series of number wheels operated by mechanism mounted upon a traveling carriage. In the illustrated embodiment of the Laganke-Smith invention, the carriage is that of a flat-platen typewriting machine, and the operating mechanism for the actuator includes the numeral keys of such machine. The totalizer is mounted independently of the carriage, and is adjustable to present it opposite any desired column of a work-sheet resting on the platen, so that as the numeral keys are depressed to print numerals within the column, the number wheels of the totalizer, corresponding in order to the numerals printed, will be moved by the actuator a number of increments corresponding to the values of such numerals. The number wheels are provided with transfer mechanism, which, when any given wheel has reached the value limit of its order, will impart a single increment of movement to the wheel of next higher order. It follows, therefore, that the actuation of the keys to print numbers in the column will automatically effect a mechanical computation, the result of which, to-wit, the total amount of a series of consecutive numbers printed by the machine, will be registered by the computing device, so that the operator may ascertain the amount or total without making mental calculations, and with absolute assurance of the accuracy of the computation.

One object of my invention, as distinguished from that of Laganke and Smith, is to produce a calculating machine includ-

ing a grand totalizer for computing the grand total of a series of columns, either in connection with or independently of a series of column totalizers or devices for computing the totals of individual columns.

Another object, subordinate to that stated, is to provide a plurality of computing devices with actuating mechanism for effecting the simultaneous operation thereof, whereby when a computing device (as for instance a column totalizer) is operated, the corresponding operation of another computing device (as for instance a grand totalizer) will be effected.

Another object is to provide a plurality of computing devices (as for instance column totalizers), an additional computing device (as for instance a grand totalizer), and operating means for imparting corresponding movement to the additional computing device or grand totalizer when each of the other computing devices or column totalizers is operated, whereby the individual columns will be totalized and the grand total of all of the columns simultaneously computed.

A further object is to provide a series of column totalizers, a grand totalizer, and actuating mechanism disposed for successive presentation to each of the column totalizers and disposed to operate the grand totalizer repeatedly as the column totalizers are operated in succession.

Another object is to provide a plurality of column totalizers with an actuator for effecting their successive operation, and a grand totalizer, with a grand actuator arranged to traverse the grand totalizer as the actuator traverses any one of the column totalizers, and to automatically return to its initial position or starting point whenever the actuator has completed the traverse of a column totalizer.

Another object of the invention is to provide a series of column totalizers, a grand totalizer, and actuating mechanism, therefore disposed to simultaneously operate a column totalizer and the grand totalizer, and arranged to be advanced by the movement of a traveling carriage.

Another object of the invention is to provide key-operated actuating mechanism for simultaneously actuating the number wheels (or their equivalents) of a column totalizer and a grand totalizer, and for effecting the

plane is of uniform cross section; that is to say, the opposing sides are parallel.

10 designates a plunger provided with a rectangular shaped notch 11 having a projection 12 in the bottom thereof. The portions of the end of said plunger on opposite sides of the notch 11 fit upon opposite sides of a projection 13 extending from the rear side of the main body portion 14 of the contact element.

The said element or member comprising the body portion 14 and the projection 13 from the rear side thereof as shown in Figs. 1, 2 and 6, is of the size and form prior to its subjection to the finishing operation. As shown in Figs. 1 and 2 the forward portion of the said contact element or member is shown as having just entered the receiving end of the opening of the die. It will be observed by reference to Figs. 1 and 2 of the drawing that when the forward end of the projection 12 is in contact with the outer end of the projection 13 the forward ends of the portions of the plunger 10 upon opposite sides of the notch 11 are slightly spaced from the surfaces of the shoulders 15 upon the contact element or member. The spaces between these shoulders and the ends of the portions of the plunger upon opposite sides 30 of the notch 11 are of a width substantially equal to the height of the projection 12 in the bottom of the notch 11.

Although no attempt has been made to show exact dimensions in the drawing, in the construction of die as actually employed by me in the dimensions of the front or receiving end of the opening of the die are .381" x .760", while the dimensions of the opening at the delivery or finishing end of the die are .369" x .742". The width and thickness of the contact elements after having been molded and baked and before having been finished according to my invention are substantially the same as the dimensions of the receiving end of the die opening, while the width and thickness of the finished contact element or part are the same as the dimensions of the delivery end of the die opening as above stated.

50 It will be understood that these dimensions of the die openings and of the contact element or member may be varied or different from the dimensions above mentioned. Reference has been made to these dimensions merely for the purpose of indicating that by forcing the contact element through the tapered die opening it is compressed and condensed and reduced slightly in cross sectional area so that when finished it is of the exact cross sectional area desired or contemplated.

As the plunger 10 forces the contact element, comprising the body portion 14 and the projection 13 therefrom through the die opening the projection 12 presses into the

metal of the projection 13 of the contact element so as to form the spring seat 16 therein, and the metal or other suitable material of the said contact element flows into the spaces upon opposite sides of the projection 12 to fill the same, as is clearly indicated in Fig. 3 of the drawing.

As the contact element or member is forced through the tapering portion 3 of the die opening the material thereof is not only compressed and condensed but simultaneously with such compressing and condensing the surfaces upon all four sides thereof are moving in contact with the inner surface of the sides of the die opening so that they are rendered very smooth. It will be seen therefore, that by the employment of the method embodying my invention in the finishing of these contact elements or parts simultaneous condensing, smoothing and polishing of the surfaces thereof are effected.

After the contact element or member has been pushed by the plunger 10 into the portion 5 of the die opening the said plunger and contact element are allowed to come to a dwell or stop. During this dwell the plunger 20 is moved forward into the delivery end of the die opening in a direction opposite to that of the plunger 10. The surface of the end of the said plunger 20 is convex and cylindrical as shown at 21 and, when forced against the opposing end of the contact element or member with sufficient force, forms a groove therein which is concave and cylindrical. This concave, cylindrical surface constitutes the contact surface of the contact element. Immediately upon the formation of this concave cylindrical surface by the pressure of the end of the plunger 20 against the contact element or member, the said plunger 20 backs out of the die opening while the plunger 10 moves forward to push the contact element from the delivery end of the opening.

It will be seen that by my invention I have provided a method for finishing the contact elements or members of commutator brushes by the employment of which an economy in time is effected; but what is more important, a contact element or member is produced the material of which has been greatly condensed, and the contact and other surfaces of which are very smooth. The lateral or side surfaces of the contact element are condensed, smoothed and polished by combined pressure between the sides of the die and the said elements and relative movement between the said element and the said die, while the smoothness of the concavo-cylindrical contact surface of said element is effected by pressure alone.

Having thus described my invention, what I claim, and desire to secure by Letters Patent, is:—

1. The method of finishing the contact ele-

frame 1, mounted to travel longitudinally of a flat platen, not illustrated, and having front and rear carriage guides 2 and 3, which slidably support a carriage 4, movable 5 transversely of the platen and supporting the printing mechanism. The upper portion of the carriage 4 is in the form of a casing 5, within which are mounted the key levers, having connection with the keys disposed 10 above the casing, and downwardly-striking type-bars, located below the casing, as is well understood in the art. The carriage 4 is drawn to the right by carriage tapes 6, and its step-by-step advance in the direction of letter spacing is permitted by the 15 operation of carriage-feeding mechanism 7, including pivoted feed yokes 7^a, one at least of which is moved to operate the carriage escapement when any one of the several 20 keys is completely depressed. The carriage-feeding mechanism 7 is indicated in Figure 4 of the drawings, and the purpose of calling attention to it in connection with the present invention is to emphasize the fact 25 that machines of the class under discussion include a traveling carriage which supports the printing mechanism and which is advanced step-by-step the distance of one letter space whenever one of the keys is completely depressed.

In carrying out my invention, I mount in rear of the machine frame 1 a guide bar 8, supported in parallelism with the frame by a pair of brackets 9, bolted or otherwise 35 rigidly secured to the rear carriage guide 3 and extended upwardly to dispose the bar 8 substantially in the horizontal plane of the top of the casing 5. Upon this guide bar, which is disposed parallel with the lines 40 of writing, are adjustably mounted a plurality of computing devices, which in the present embodiment of the invention may be designated column totalizers 10 and 11, and an additional computing device which may 45 be termed a grand totalizer 12. The column totalizers, of which any desired number may be employed, are designed to compute the totals of individual columns of figures, opposite which they have been located by 50 their adjustment upon the bar 8. The grand totalizer 12 is designed to compute the grand total of the several columns, and is preferably mounted upon an extended end 55 of the bar 8, to dispose it beyond one side of the printing area of the platen.

The computing and registering mechanism, within the casing 13 of each totalizer, will be hereafter described in detail. For the present, however, it is sufficient to call 60 attention to the fact that this mechanism comprehends, as is usual in this class of devices, a series of denominational members, digit carriers or number wheels *a*, *b*, *c*, *d*, *e*, *f*, *g*, *h*, and *i*, designed to register hundredths, tenths, units, tens, hundreds, thou-

sands, ten thousands, hundred thousands and millions, the tenths and units wheels *b* and *c* being spaced apart sufficiently to provide an intermediate decimal space. Each of these wheels is provided upon its periphery with the digits, 9 to 0 inclusive, preferably formed in or upon the end faces of peripheral teeth, one digit of each wheel being observable through a sight opening 14 in the downwardly-curved front end of the top wall 15 of the register casing. Each of the number wheels is arranged to make nine-tenths of a complete revolution independently of the other wheels of the series, to present its digits successively before the sight opening, and during its last increment of movement engages the adjacent wheel at the left and rotates it a single increment or step, after which the first-named wheel may again rotate independently for nine-tenths of a complete rotation before again advancing the adjacent wheel at the left a single step.

Since the wheels of the entire series are related to one another in the manner stated, it follows that mechanical computations in addition may be effected by moving the wheels, corresponding in order to the order of the numerals composing the numbers to be added, a number of increments corresponding to the unitary values of such numerals. Thus, suppose it is desired to add 432 and 234, the ciphers of all of the wheels being disposed opposite the sight opening 14. The wheel of the third order, to-wit, the wheel *e*, will be rotated four increments, presenting the numeral 4 at the sight opening; the wheel *d* of the second order will be rotated three increments and the wheel *c* of the first order two increments or steps. The numerals exposed before the sight opening will now read 432, corresponding to the first number. The second number 234 will now be added by imparting to the third order wheel *e* two additional increments of movement, to the second order wheel *d* three increments and to the first order wheel *c* four increments, thus causing the numerals presented before the sight opening to read 666, the sum of the two numbers.

Since the numerical value of each order is 10, and since each wheel during its last increment of movement will, as heretofore explained, impart a single increment of movement to the next adjacent wheel to the left, it follows that when the number registered reaches the limit of the numerical value of a given order, the rotation of the adjacent wheel will effect the registration of a numeral of the next higher order. Thus, assuming the first order or unit wheel *c* to have been given nine increments of movement, causing the presentation of the numeral 9 before the sight opening, the next or tenth increment of movement will present

the 0 on said wheel before the sight opening, and by the automatic engagement of the wheel *c* with the wheel *d* of the second order, the latter wheel will be moved a single increment to present the numeral 1 of the second order before the sight opening, the presentation of the two digits 0 and 1 in the first and second orders effecting the registration of the number 10.

10 It will of course be understood that the mechanisms within the casings of the column totalizers and the grand totalizer are identical in construction, and may be said to constitute the computing or adding mechanism proper which is mounted independently of the carriage. Upon the carriage is mounted another portion of the computing mechanism, to-wit, actuating mechanism presentable in succession to the number 15 wheels of each of the column totalizers by the step-by-step advance of the carriage, and operatively related to actuating mechanism for the grand totalizers, presentable to the number wheels thereof in succession as the 20 first-named actuating mechanism traverses any one of the column totalizers, it being understood that these actuators are designed to rotate the number wheels of the totalizers and grand totalizer in proportion to the numerical 25 values of the numerals embraced by the computations. This arrangement is one of the novel characteristics of the invention viewed as a calculating machine, since the traveling carriage supporting the operating 30 mechanism for the number wheels is not necessarily the carriage of a typewriting machine. It is contemplated, however, to utilize key-operated number wheel actuators, and although it is not essential that 35 these keys be arranged to operate the printing devices, the illustrated embodiment of the invention comprehends the utilization of the numeral keys of a typewriter as the operating means for the actuators.

40 Having a general understanding of the arrangement and mode of operation of the totalizers and grand totalizer, we may now consider the arrangement of the actuators for the number wheels and the mechanism 45 for effecting an operative connection between the actuators and the numeral keys of the typewriter, it being understood that the combined typewriting and computing machine, to be specifically described, is intended to print several columns of numbers, 50 as well as to compute and register the column totals and the grand total of the numbers recorded. It may be stated at this point that the actuator of the grand totalizer 55 is operatively connected to the actuator for the column totalizers, and that the specific mechanism for operating the last-named actuator from the numeral keys does not constitute part of my invention. On the contrary, the specific construction of the total- 60 izers, the mounting of an actuator on the traveling carriage for presentation to a totalizer, and the connections between the numeral keys and said actuator, all as shown in the accompanying drawings, are 65 features of the invention of Laganke and Smith, and are fully disclosed in their application aforesaid. It appears to be unnecessary, therefore, to do more than describe in a general way the mechanism connecting the 70 keys with the actuator for the column totalizers, and to then describe with greater particularity the relative arrangement of the grand totalizer and the means whereby its actuator is operated in synchronism with 75 the actuator of the column totalizers.

Above the key levers 16, which latter are disposed within the casing 5, as is well understood in the art, is mounted a swinging yoke 17 (see Figure 4) having a series of 80 graduated contact plates 18, each located directly above a numeral key lever and designed to be engaged by the latter to swing the yoke. Each of the levers is intended to effect the rotation of a number wheel to an 85 extent corresponding to the numerical value printed, and it is for this reason that the plates 18 are graduated, in order that the yoke, which is a motion transmitting element common to the several keys, will be 90 moved a different distance upon the depression of each key. Upstanding from the bottom of the casing 5 is a plunger guide 19, within which is mounted for vertical reciprocation a plunger 20, designed to be oper- 95 ated by the yoke and arranged in turn to swing a rack lever 21, mounted above the casing 5, and geared to the master wheel or actuator 22 of the column totalizers. At the lower end of the plunger 20 is formed an 100 angular arm 23, disposed in the path of a plate 24, secured to the yoke 17. When the yoke is elevated by the depression of a key, the plunger will be raised in an obvious manner and will be dogged by a pivoted dog 105 110 25, mounted on the plunger guide and disposed to engage a rack 26, formed in one side face of the plunger. Upon the complete depression of a key one of the feed yokes will strike the front end of a lever 27, to 115 swing the same for the purpose of causing a release finger 28 thereon to strike the tail piece of the dog 25, to move the same out of engagement with the rack and thus permit the retraction of the plunger. 120

Overrunning of the master wheel 22 is prevented by a checking arm 29, connected to the lever 27 by a link 30, and disposed to be swung into engagement with the master wheel as the latter completes its movement. 125

The actuating or rack lever 21 is fulcrumed on a short horizontal shaft 31, supported by posts 32, constituting elements of a supporting frame, the base plate 33 of which is bolted or otherwise secured to the 130

top of the casing 5 at the rear side thereof. At the rear end of the lever 21 is formed a segmental rack 34, meshing with a pinion 35, formed upon or rigidly attached to a short 5 horizontal sleeve 36, mounted to rotate upon a shaft 37, extending between posts 38 up-standing from the rear end of the base plate 33. At the end of the sleeve 36, opposite the pinion 35, is formed or attached a ratchet 10 wheel or disk 39, the teeth of which are designed to be engaged by a pawl 40, carried by the master wheel 22 and urged toward the ratchet wheel by a spring 41. The master wheel 22 is mounted upon the shaft 37 15 beyond one end of the sleeve 36, and is intended to mesh with successive number wheels as the carriage is advanced in the direction of letter spacing. Reverse rotation of the master wheel is prevented by a pawl 20 42, preferably mounted upon one of the posts 38 and engaging a ratchet disk 43, fixed to the master wheel and having its teeth disposed oppositely to the teeth of the ratchet wheel 39.

25 The depression of one of the numeral or digit keys of the typewriter effects more or less elevation of the yoke and plunger through the swinging of a key lever, and the consequent elevation of the rear end of 30 the rack lever 21, engaged by the plunger, will depress the segmental rack 34. The depression of the rack will rotate the pinion 35, and the ratchet wheel 39 moving with said pinion will engage the pawl 40 to rotate 35 the master wheel, and thereby impart movement to one of the number wheels, the extent of such movement corresponding of course to the movement imparted to the yoke by the particular key lever actuated.

40 It has been stated that the actuator of the grand totalizer, which for the purpose of distinguishing it from the actuator 22 may be termed the grand actuator or grand master wheel, is operated from and in syn- 45 chronism with the master wheel of the column totalizers. It will therefore be apparent that some means must be provided for disconnecting the latter from the numeral keys while traversing the interval be- 50 tween two columns, or, which is the same thing, between two column totalizers, as otherwise the grand totalizer would be operated upon the depression of the numeral keys to print numerals other than those de- 55 signed to be embraced within the computa- tion.

Various devices for accomplishing this end might be employed, but by preference a rock-shaft 44 is journaled in a sleeve- 60 bearing 45 at the rear end of the casing 5, and is provided at its opposite ends with a yoke-elevating cam 46 and a trip arm 47. The cam 46 is disposed to engage the under side of a fixed part of the yoke 17, 65 as, for instance, the horizontal portion of an angular plate 47 secured thereto. En- circling the rock-shaft is a spring 48, se- cured at its opposite ends to the sleeve 45 and the cam 46, respectively, and tending constantly to urge the cam in a direction 70 to elevate the yoke 17, for the purpose of removing the operating connections of the computing device entirely out of the paths of movement of the key levers. The trip arm 47, located at the rear end of the shaft 75 44, is mounted loosely thereon adjacent to one side face of a head 49, fixed to the shaft and provided with a ledge 50 opposed to one end of the arm 47. This ledge con- stitutes a stop limiting the movement of 80 the arm 47 relative to the shaft 44 in one direction, but such independent movement of the arm in the opposite direction is per- mitted by the rounding of one corner there- of, as indicated at 51. (See Figure 6.) The 85 retention of the arm in its normal position is insured by a spring 52, secured at one end to the head and bearing against one side of the arm.

When the master wheel is not located op- 90 posite a column totalizer, that is to say, when the printing point of the machine is located outside of the columns being total- 95 ized, the cam 46 will hold the yoke 17 out of engagement with the key levers, so that no movement will be imparted to the master wheel from the numeral keys when the latter are depressed for the purpose of print- 100 ing numbers other than those embraced with- in the desired computation. When, how- ever, the advance of the carriage brings the master wheel adjacent to a column totalizer, the upper end of the trip arm 47 is brought into contact with a trip flange 53, pref- 105 erably depending from the front of each column totalizer. (See Figure 3.) As the carriage continues to advance the trip arm will be swung back, and as its independent movement is prevented by the ledge 50, the rock-shaft will be rotated and the cam 46 110 turned down to a horizontal position, for the purpose of restoring the operative re- lation between the actuator yoke 17 and the key levers by the time the master wheel moves into operative relation with the num- 115 ber wheel of highest order.

This relation of the parts will be main- tained while the master wheel is traversing the series of number wheels, because the trip arm will be in engagement with the 120 bottom wall of the flange 53, and will not pass therebeyond until the master wheel has moved out of coincidence with the number wheel of lowest order. When, however, the master wheel has moved beyond the totalizer, 125 and the trip arm has moved beyond the flange by reason of the step-by-step advance of the carriage, the spring 48 will restore the yoke-elevating cam 46 to its normal posi- 130 tion to again relieve the numeral key levers

of any unnecessary burden. During the retraction of the carriage to begin a new line of writing, the trip arm 47 will again contact with the trip flange 53, but instead of rocking the shaft 44 as before, will rock independently of the shaft in opposition to the spring 52, which latter will restore the arm to its normal upright position when the flange has been passed.

10 Thus the machine may be said to comprehend a plurality of column totalizers, an actuator therefor, a series of keys normally out of operative relation with the actuator, a traveling carriage, and means for automatically effecting an operative relation between the keys and the actuator when the latter is presented to either of the totalizers during the advance of the carriage.

15 In addition to the automatic means for elevating and depressing the yoke 17, I provide a second yoke-elevating cam 54, opposed to the under side of the yoke preferably at one end thereof, and mounted upon a manually-operated rock-shaft 55, journaled in a bearing sleeve 56 and extended through one end of the casing 5, beyond which it is provided with a knurled head 57. The cam 54 constitutes manually-operated means for totally disconnecting the keys from the computing mechanism when it is not desired to utilize the latter.

20 We have now seen by what instrumentalities provision is made for operating the number wheels of the several column totalizers by an actuator or master wheel, automatically connected with operating keys whenever it is presented to a column totalizer. It is now in order to describe the means for operating the number wheels of the grand totalizer in synchronism with corresponding number wheels of any column totalizer with which the master wheel 22 is engaged.

25 The grand totalizer 12 is mounted, as heretofore stated, upon one end of the bar 5, and its side walls are extended forwardly to form bearing brackets 58, through which the actuator shaft 37 is extended. Upon this shaft, between the brackets 58, is splined the grand master wheel 59, which, like the column master wheel 22, is toothed for direct engagement with the number wheels of the adjacent totalizer. Since the grand master wheel is splined upon the actuator or master wheel shaft 37, it necessarily rotates with the shaft, but the latter is capable of independent longitudinal movement, so that while the grand master wheel 59 rotates in synchronism with the column master wheel 22, the latter is capable of such independent movement as is necessary to present it to successive column totalizers. In other words, this character of mounting of the grand master wheel limits its lateral or sideways movement to the confines of the grand totalizer, and permits the column master wheel

22 to have unrestricted movement entirely across the printing area of the platen, and at the same time maintains that operative relation between the wheels which insures their rotary movement in unison. Beside this synchronous movement, the two master wheels must also be advanced in unison during the traverse of a column totalizer by the master wheel 22, as it is obvious that the grand master wheel should operate that number wheel of the grand totalizer which corresponds in order to the number wheel of the column totalizer which is being rotated by the column master wheel.

30 We have seen that the advance of the column master wheel from one number wheel to the wheel of next lower order, is effected by the step-by-step advance of the carriage. I therefore utilize this element for the corresponding step-by-step advance of the grand master wheel. Extending between the brackets 58, in a plane somewhat below and in advance of the shaft 37, is a short shaft 60, upon which is mounted a laterally-movable shifter 61, having a bifurcated upper end 62, embracing the adjacent side of the master wheel 59, the master wheel and shifter being normally retained

35 opposite the number wheel of highest order by springs 63 and 64 encircling the shafts 37 and 60, and interposed between the right hand bearing bracket and the master wheel and shifter, respectively. The shifter 61 is designed to be operated from the carriage, to advance the wheel 59 step-by-step to present it successively to the several number wheels of the grand totalizer. Said shifter is therefore provided with a depending tail-piece 65, designed to be engaged by a projection preferably in the form of a block 66, 40 adjustably retained as by a set screw 71, or its equivalent, upon what may be termed a shift bar 67, extending horizontally from the adjacent end of the carriage 4, and preferably secured to the rear wall of the casing 5, as shown in Figure 1. The outer end of the bar 67 is guided by a bracket arm 72, upstanding from the machine frame beyond the grand totalizer, and provided at its upper end with a square opening 73 for the reception of the bar 67. One of the projections or blocks 66 is provided for each of the several column totalizers, and by the adjustment of these blocks upon the bar 67, they may be so arranged that whenever the 45 column master wheel 22 arrives opposite the number wheel of highest order of any one of the several column totalizers, one of the blocks 66 will be in engagement with the shifter 61, so that as the carriage is advanced 50 one step, both master wheels will be advanced in unison to the next lower number wheels of the column totalizer and grand totalizer, respectively. Thus assuming that the master wheel 22 has moved into coinci-

dence with the number wheel at the left-hand end of one of the column totalizers, one of the blocks 66 will be in engagement with the tail piece of the shifter 61, as shown in Figure 12.

With the parts in these positions the depression of a key will effect more or less rotary movement of the actuator 22 and synchronous movement of the grand master wheel 59. Synchronous movement will thus be transmitted to corresponding number wheels of a column totalizer and the grand totalizer, and as the key rises the carriage will be advanced the distance of one letter space. This advance of the carriage will obviously move the master wheel 22 into coincidence with the next lower number wheel of the column totalizer, and will also advance the shift bar 67 a like distance. The block 66 carried by the bar and engaging the tail-piece 65 of the shifter 61 will thus cause sufficient lateral movement of the shifter to advance the grand master wheel 59 to the next lower number wheel of the grand totalizer, against the resistance of the springs 63 and 64. The depression of another key will now effect the synchronous operation of corresponding number wheels of a column totalizer and the grand totalizer as before, and the repetition of the described operations will finally present the two master wheels to the number wheels of lowest order. At such time, the tail-piece 65 of the shifter will be disposed in contact with a trip device having the form of a cam projection 68, extending from the right-hand bearing bracket 58. Upon the next advance movement of the carriage, both master wheels will move beyond the number wheels of the totalizers, and the tail-piece 65 of the shifter (riding over the inclined face 69 of the cam 68) will be swung on the shaft 60 as an axis, to move said tail-piece out of engagement with the block 66, which, as we have seen, has effected the advance of the shifter and grand master wheel from one side of the grand totalizer to the other. As soon as the tail-piece 65 of the shifter moves out of engagement with the block or projection 66 on the shift bar, the springs 63 and 64 will retract the master wheel and shifter, restoring the normal positions of these parts and presenting the tail-piece 65 in position to be engaged by the next block on the shift bar, when, by reason of the advance of the carriage, the master wheel 22 arrives opposite the highest number wheel of the next succeeding column totalizer. As the numbers are recorded in this second column, the second column totalizer and the grand totalizer will be synchronously operated in a manner exactly similar to the operation just described in connection with the first column totalizer, and the same operation will be repeated when numbers are recorded in any addi-

tional column for which a column totalizer has been provided, it being obvious that the recording of numbers outside of the columns intended to be embraced within the computation will not affect any of the totalizers, 70 since the numeral keys will be out of operative relation with the master wheels whenever the printing point of the machine is disposed in the intervals between the columns.

It will now be noted that while the column totalizer is concerned only with the numbers printed in its individual column, the grand totalizer is operated whenever a number is recorded in any one of the several columns for which column totalizers are provided, and it follows therefore that while the numbers in the individual columns will be embraced by the computations of the column totalizers, the numbers recorded in all of the columns will be embraced by the computation effected by the grand totalizer, the latter registering the grand total of the several columns and the former the column totals. The retraction of the carriage 4, to begin a new line of writing, will re-position the master wheel 22 in position to be again advanced to successive column totalizers, and as the shift bar 67 moves back with the carriage the blocks will be again positioned to the left of the shifter 61, the rear front corner 70 of each block being cut away at an angle to compel the tail-piece 65 to ride over the blocks as the latter are presented thereto during the retraction of the carriage.

It is of course necessary to provide means for resetting the totalizers at zero after the result of a given computation has been ascertained and transferred to the work-sheet, and while manually-operated resetting mechanism, such as is disclosed in the Laganke-Smith application hereinbefore identified, may be utilized, and in fact is shown in connection with the grand totalizer, I prefer to equip the column totalizers at least with automatic resetting mechanism, to a proper understanding of which it is necessary to have some idea of the specific construction and operation of the totalizer construction. Therefore before proceeding with the description of the resetting mechanism, I shall describe as briefly as is consistent with clearness the manner in which the number wheels are mounted and the mechanism directly associated with the number wheels, which mechanism, though not constituting part of the present invention, is cooperatively connected with the novel resetting mechanism to be hereinafter described.

Within alined openings in the side walls of each totalizer casing 13, are located bearing collars 74 and 75, within which is journaled the number wheel shaft 76, rotatably supporting the several number wheels. (See Figure 8.) This shaft is normally stationary, and upon it are fixed a series of sub-

stantially disk-shaped transfer cams 77, one of which is located within the recessed side face of each wheel. Each wheel is provided, upon the bottom face 78 of its recess, with a pivoted transfer pawl 79, (see Figures 8, 9 and 10) having a tail-piece 80, urged outwardly by a flat spring 81 and formed at its opposite end with a beak 82. The major portion of each transfer cam is concentric with the shaft 76, but between the opposite ends of this plain portion 83 of the cam is formed a depression 84, at one end of which is defined an angular resetting notch 86. The relation of each transfer pawl to its cam when the wheel carrying the pawl is registering 0, is shown in Figure 9. Assuming the wheel shown in this figure to be the wheel *g*, to the right of the wheel *f* with which the actuating wheel is engaged, it will be seen that the rotation of the latter in the direction of the arrow will cause the beak 82 of the transfer pawl (shown in dotted lines) to ride upon the plain face 83 of the cam during eight increments of movement of the wheel, that is to say, while the numbers 1 to 8 are successively presented before the sight opening. At the end of the eighth increment of movement, the beak will drop into the resetting notch 86, and during the next or ninth increment of movement (which presents the digit 9 of the wheel *f* to the sight opening) the beak of the pawl will travel down into the depression 84 of the cam to engage a tooth of a ratchet wheel 87, formed (as shown in dotted lines) upon the adjacent side face of the number wheel *g* of next higher order. Thus, an engagement will be effected between the two wheels, (see Figure 10) so that as the final increment of movement is imparted to the wheel *f*, a corresponding increment of movement will be imparted to the wheel of next higher order, to-wit, the wheel *g*.

The springs 81 are employed for the purpose of holding the beaks of the transfer pawls against the edges of the cams, but the positive engagement of each pawl with a tooth of the adjacent ratchet wheel at the proper time, is effected by a slight swell or projection 88, formed on each transfer cam adjacent to the resetting notch thereof. (See Figures 9 and 10.) As the beak of the pawl approaches the depression 84 of the cam, its tail piece rides upon the projection 88, which positively swings the beak of the pawl into the depression to engage the tooth of the adjacent ratchet disk as the pawl advances.

It will be noted by reference to Figures 9 and 10 that the transfer cams are of greater diameter than the ratchet wheels 87, except where said cams are depressed to provide for the projection of a single tooth to be engaged by a pawl when the latter is moved down to the bottom of the depression

84 in the manner heretofore stated. It will therefore appear that during the last increment of movement of the wheel *f*, the beak of its pawl will be moving up one inclined side of the depression, and will thus be disengaged from the tooth of the ratchet wheel before the next increment of movement of the wheel *f* is commenced. By reason of this relation of the parts, each cam will serve to hold the pawl of its wheel out of engagement with the ratchet disk of the adjacent wheel, except during the tenth increment of movement, so that each wheel will have independent movement for nine-tenths of each complete rotation, and will have cooperative engagement with the next adjacent wheel to the left during the final tenth of each rotation.

For the purpose of locating the registering wheels with accuracy, so that the digits will always be disposed in exact alinement before the sight opening 14, I provide what may be termed locating plates 89, disposed to slide in suitable guideways 90, formed in horizontal guide plates 91, secured rigidly within the casing 13. (See Figures 8, 9 and 10.) One of these plates is provided for each number wheel, and each plate is formed at its front end with a pair of pallets 92 and 93, which engage the teeth of the adjacent number wheel in a manner to locate the latter accurately in proper position and to hold it until positively rotated by the master wheel or by the adjacent number wheel. The function of these plates 89 will be clear when it is considered that the transfer pawl engaging a tooth of an adjacent wheel must move entirely out of contact with said tooth by the time the tooth carrying the pawl completes its revolution. It is therefore clear that unless locating means other than the pawl is provided, the final movement of the wheel, to which motion is communicated by the pawl, would be uncertain, by reason of the precarious engagement between the pawl and the tooth at such time, and there would be some consequent uncertainty as to the accurate location of the driven wheel.

The locating plates are therefore so constructed that after the pawl of what may be termed a driving wheel positively moves the engaged or driven wheel a given distance, said driven wheel will be moved positively by its locating plate independently of the pawl, so that while both wheels will be positively located, the edge of the engaged tooth will have entirely disappeared within the edge of the cam by the time the movement of the pawl is completed. By reference to Figure 10, it will be seen that when the beak of a pawl is in engagement with the tooth of the adjacent wheel and is ready to propel the latter, the pallets 92 and 93 will be in engagement with the teeth of the wheel to be driven, to hold it in posi-

tion until positively actuated. If now the driven wheel is positively rotated by its engagement with the driving wheel carrying the pawl, its locating plate will be forced 5 rearwardly against the resistance of a spring 94, one of which is provided for each of the plates. The plate, being thus moved back to the position shown in Figure 9, will permit the rotation of the driven wheel, and just 10 before the latter has reached the end of its increment of movement, and while the pawl is still in engagement with the ratchet tooth, the upper corner of one of the peripheral teeth of the driven wheel, (see *x*, Figure 9) 15 will pass the point of the pallet 93 and will be presented to an inclined impulse face 95, formed on the pallet. The impulse face 95, being inclined with respect to the direction of movement of the locating plate, will, as 20 said plate is urged toward the wheel, compel the downward movement of the engaged tooth a sufficient distance to accurately locate the wheel, and to cause the ratchet tooth thereof to be entirely disengaged from the 25 beak of the pawl and to be withdrawn within the edge of the cam disk. When the plate 89 has finally come to rest after locating the wheel, the upper and lower pallets 92 and 93 will be in engagement with the teeth of the 30 wheel, as shown in Figure 10, to hold said wheel in its properly located position.

For reasons fully explained in the application of Laganke and Smith, it is desirable to provide positive locking mechanism for 35 the number wheels. This mechanism includes a series of locking dogs 96, one for each of the number wheels with the exception of *a*, as this wheel is never operated by movement transferred from another. These 40 dogs are located below the wheels and are mounted on a shaft 97, extending between the side walls of the casing 13. Each dog is yieldingly urged to its disengaged or unlocked position by a spring 98. In such 45 position of the dog, a thin trip plate 99, located at one end thereof, extends in a plane between the wheel served by the dog and the adjacent wheel of next lower order. This disposition of the trip plate brings it 50 into the path of movement of a trip pin 100, extending laterally from a tooth of the wheel of lower order. Each trip pin extends from that tooth of the number wheel which bears the digit 4, in order that said pin will engage 55 the trip plate of a dog during the movement, of the wheel carrying the pin, from 9 to 0.

We have already seen that the movement 60 of any number wheel from 9 to 0 will be accompanied by a single increment of the adjacent wheel of higher order, and it will now be observed that since the trip pin 100 engages the trip plate of a dog during this 65 same interval, the result will be that when

the adjacent wheel, and will at the same time operate the dog of said wheel to lock it positively when its single increment of movement has been completed. This will be clear by reference to Figures 9 and 10. In 70 Figure 10 the wheel *g* is about to be advanced one increment by the wheel *f*, whose transfer pawl is shown in dotted lines. As the wheel *f* advances under the impulse of the master wheel, its pawl will pick up and 75 advance the wheel *g*, and its trip pin 100 will engage the trip plate 99 of the dog 96, serving the wheel *g*, so that the dog will be rocked against the resistance of the spring 98, and will have its rear end thrown up to 80 its engaging position, as shown in Figure 9. This movement will occur just as the impulse face 95 of the locating plate of the wheel *g* is about to advance for the purpose of locating the wheel. Therefore, the advance of the locating plate will assure the complete movement of the wheel *g*, and the dog will prevent excessive movement thereof, one tooth of the wheel being rigidly retained between the engaging end of the dog 85 and the impulse face of the locating plate. It should be noted at this point that as the dog is swung to its engaging position, the trip pin which has imparted positive movement to it will pass over and beyond the trip 90 plate to the position indicated in Figure 9. At this time the wheel carrying the pin, as for instance the wheel *g*, will be registering 0, and may therefore be again rotated nine-tenths of a complete revolution before coming 100 into contact with the trip plate of the dog, in the event that said dog has in the meantime been restored to its unlocked or disengaged position.

Since the passage of the trip pins beyond 105 the trip plates of the dogs would obviously permit said dogs to be immediately retracted by their springs, it is desirable to provide means for holding the dogs in their engaged positions. Such means comprehends the employment of a series of dog-retaining plungers 101, mounted in suitable guides 102, extending across the casing 13 and urged forwardly by springs 103, each encircling a plunger and bearing at its ends against one 110 of the guides and a shoulder formed on the plunger, respectively. When the dogs are in their unlocked positions, as indicated in Figure 10, they are disposed to hold the plungers in their retracted positions, but immediately upon the movement of a dog to its engaging position, its plunger moves forward to engage the under side of the elevated end of a dog, and thus prevents its retraction when the trip pin moves beyond the 115 plate. As the number wheels are operated in succession during the travel of the carriage in the direction of letter spacing, such of said number wheels as are advanced by transferred movement will be positively 120 advanced by transferred movement will be positively 130

locked by the dogs and will remain locked during the advance of the carriage, since it is evident that no number wheel can be twice operated by movement transferred to it from another number wheel during a single travel of the actuator across the totalizer.

It is necessary, however, to unlock the number wheels before another number is added to that already registered, since it would otherwise be impossible to rotate the wheels by either transferred movement or by the direct action of the master wheel. Many ways of accomplishing the desired end might be suggested, since the simple retraction of the dog-retaining plungers 101 will permit the springs 98 to instantly retract the dogs. We prefer, however, to provide automatically-operated means for unlocking the number wheels upon the retraction of the carriage. The illustrated embodiment of the unlocking mechanism comprehends the employment of an unlocking frame 104, mounted to slide in horizontal guide grooves 105, formed in the side of the casing, and engaging at its rear end a series of pins 106, depending from the plungers. The pins 106 are received at their lower ends within guide grooves 107, designed to prevent their lateral displacement. The unlocking frame 104 is of light open form, and is provided at its front end with a vertical flange 108, at the lower edge of which is located a horizontal ledge 109. (See Figures 1, 3, 9 and 10.) By moving the unlocking frame rearwardly to the position indicated in Figure 10, such of the plungers as are in their forward positions will be retracted, permitting the dogs to drop back out of engagement with the wheels. This movement of the frame may be effected manually, but since, as heretofore explained, its automatic retraction is contemplated, I provide what may be termed an unlocking cam 110, in the form of a plate movable with the carriage and preferably hinged between a pair of ears 111, projecting rearwardly from the base plate 33 of the supporting frame for the actuator.

The cam 110 is normally retained in a horizontal position by a stop lug 112, projecting from the hinged edge thereof and engaging the under side of the plate 33. In this position of the cam it is disposed in the horizontal plane of the ledge 109 of the unlocking frame, and when retracted with the carriage its inclined face 113 contacts with one corner of the ledge, and consequently forces the unlocking frame rearwardly as the retraction of the carriage continues. Thus, whenever the carriage is retracted after having advanced the master wheel of the computing mechanism across the series of number wheels of the column totalizers, said wheels will be automatically unlocked by the successive actuation of the unlocking frames, and may be again operated in the

manner heretofore described, as the carriage again advances in the direction of letter spacing. It is evident that as the carriage advances, the unlocking cam 110 must not occupy an obstructing position with respect to either unlocking frame, as this would prevent the forward movement of the frame, and the retaining plungers would in consequence be prevented from moving forward to retain the dogs. It is for this reason that the cam is hinged to permit it to occupy a position above the ledge 109, during the advance movement of the carriage. The under side of the cam 110, at the end thereof opposite the inclined face 113, has a beveled face 114, which rides up on the left-hand end of the ledge 109, and thus elevates the unlocking cam to permit it to ride over the ledge as the carriage advances.

We have now seen how the transfer movements of the number wheels are effected, the manner in which the wheels are accurately located, the provision made for positively locking the wheels, and the arrangement of the automatic means for unlocking the wheels by the retraction of the carriage. It therefore remains to be described in what manner the computing mechanism is reset or restored to zero after any given computation has been completed.

Keyed or otherwise fixed upon the end of the shaft 76 of each of the column totalizers is a resetting head 115, located just beyond the side wall of the casing and provided with a pawl 116, disposed to be engaged by a ratchet 117 formed integral with or otherwise fixed to a cam 118, and a pinion 119 located beyond the cam. The pinion 119 is disposed for engagement by a reciprocatory rack bar 120, keyed in suitable bearings and urged forward by a spring 121, or its equivalent, which may be mounted upon the side of the casing and is disposed to bear against the rear end of the rack bar, as shown in Figure 13. Rearward movement of the rack bar against the resistance of the spring 121 is effected by what may be termed a resetting arm 122, movable with the carriage 4, and contacting with an anti-friction roller 123, mounted at the front end of the rack bar.

The resetting arm 122 is disposed at an inclination with respect to the rack bar, and acts as a cam, serving (as the carriage is retracted) to move the rack bar rearwardly, and thus rotate the pinion 119. For the purpose of permitting the arm 122 to ride past the rack bar without engaging the latter during the advance movement of the carriage, said arm is pivotally mounted upon a stud 124, extending from a boxing 125 mounted upon a short rock-shaft 126, and having a stop flange 127. The arm 122 is urged to its normal position by a spring 128, and in such position the stop shoulder 129 130

formed on the arm engages with the flange 127, to hold the arm rigidly in proper position to effect the rearward movement of the rack bar. When, however, the carriage 5 is advanced, the arm 122 striking the roller will swing back against the resistance of the spring 128, and will pass by the rack bar without moving the latter. It is sometimes desirable to retract the carriage without 10 operating the resetting mechanisms of the column totalizers, and this contingency is provided for by providing the boxing 125 with a thumb piece or handle 130, which may be depressed to rock the shaft 126, and 15 thus elevate the resetting arm out of the path of the rack bar.

When one of the rack bars is moved rearwardly by the resetting arm 122, the adjacent pinion 119 is rotated. The ratchet 20 wheel 117, moving with the pinion, will engage the pawl 116 on the resetting head 115, and as said head is fixed to the shaft 76, rotary movement will be imparted to the latter and to the transfer cams mounted 25 thereon. Since the resetting notches 86 of the several transfer cams are accurately aligned, and since the transfer pawls bear an identical relation to the number wheels, the rotation of the shaft 76 will effect the 30 engagement of the resetting notches with the beaks of the pawls, and when such engagement is effected the similar digits of the several number wheels will be aligned. This result will of course be effected by a 35 complete revolution of the shaft, but as the starting positions of the pawls are two increments of movement in advance of the resetting notches, (see Figure 9) the throw of each rack bar is sufficient to move the 40 shaft somewhat more than a complete rotation, in order that the resetting notches of the cams will move a sufficient distance to properly position the pawls and to present the several number wheels at zero, after 45 which the shaft may be turned back to present the resetting notches the distance of two increments in rear of the beaks of the pawls. This backward movement of the shaft 76 is effected at the end of the retractive movement of the rack bar 120 under 50 the impulse of the spring 121.

The rack bar is provided at its rear end with a projection 131, which, as the rack bar is approaching the limit of its retractive movement, contacts with a pin 132, projecting radially from the shaft 76 at a point beyond the pinion 119. The normal position of this pin is vertical, as shown in Figure 13, and when the wheels have been reset 55 the pin will have made one complete revolution, plus the distance of two increments of movement of the shaft, and will assume the position shown in Figure 15, which is slightly beyond the vertical. Therefore, as the rack 60 bar moves forward after having effected

the resetting of the wheels, the projection 131 thereon will contact with the pin 132, restoring it to its normal vertical position, and thereby rotating the shaft in the reverse direction and moving the cams back 70 to properly position the resetting notches thereof. It will of course be evident that since the pinion 119 and the ratchet wheel 117 are mounted loosely on the shaft, reverse rotation of these elements, as the rack 75 bar moves forward, will not be accompanied by corresponding movement of the shaft.

The position of the unlocking cam upon the carriage is such that as said carriage is retracted, the unlocking frame 104 will be 80 retracted before the resetting arm is brought into contact with the front end of the rack bar. The number wheels will therefore be automatically unlocked prior to the automatic resetting thereof, but it will be remembered that whenever a wheel is moved to present 0 before the sight opening, the dog of the next adjacent wheel will be automatically thrown into engagement therewith, and the plungers will spring forward 85 to hold the dogs in engagement. It is evident therefore that unless some means are provided for holding the plungers back when the wheels reach their reset positions, said wheels will be automatically locked at 90 the end of the resetting operation and will be incapable of actuation during the next 95 advance movement of the carriage.

It is for this reason that the cam 118 has been provided. This cam is disposed in operative relation to what may be termed an unlocking lever 133 of bell-crank form, fulcrumed on the side of the register casing. One end of this lever is disposed against the periphery of the cam 118 and its opposite 100 end is arranged in operative relation to a projection 134, extending through the side of the casing from the unlocking frame 104. Normally the lever 133 engages a depression 105 135 in the face of the cam 118, but as the latter rotates during the resetting of the wheels, the depression will move away from the lever, and the latter will be rocked to retract the unlocking frame, which thus obstructs the forward movement of the 110 plungers. When the wheels are completely reset, the cam will be in position to hold the lever 133 and the unlocking frame in their 115 retracted positions, and consequently while the locking dogs are positively moved into 120 engagement with the number wheels, when the latter reach their reset positions, the plungers will be prevented from moving forward to retain the dogs, and the latter will consequently drop back to their disengaged positions as soon as the number 125 wheels are relieved of tension by the reverse movement of the shaft. When, however, the rack bar has returned to its forward position, the cam 118 will have been moved 130

to its normal position, shown in Figure 3, to permit the forward movement of the unlocking frame. Therefore, at the completion of the resetting operation the forward movement of the plungers will be unrestricted to permit the performance of their proper functions as retaining devices for the dogs, when the latter are automatically thrown up to lock the wheels during the advance of the carriage.

The resetting mechanism illustrated in connection with the grand totalizer is identical with that disclosed in the Laganket-Smith application aforesaid, and since an understanding thereof is unnecessary in connection with my present invention, the description thereof has been omitted.

At this point attention may be directed to the fact that the flanges 53 of the column totalizers constitute trips which are independently adjustable parallel to the line of writing and control the operative connection between the numeral keys and the actuator and which serve by their adjustment to determine the location of the columns to be computed, that is to say, the location of the columns on the work sheet. Furthermore, when considered in connection with the grand totalizer 12, these strips 53 may be said to be adjustable independently of said totalizer for the purpose of determining the location of the several columns to be included in the computation effected by said grand totalizer or computing device. Furthermore, either of these trips 53 which is adjustable independently of the computing device 12, will be seen to control means, to wit, the yoke 17 and associated parts, whereby an operative relation will be established between the computing device and its operating mechanism, when the printing mechanism is disposed to print in a given column, and whereby an inoperative relation of said parts will be automatically established to permit digits to be printed beyond the column, that is to say, to the right thereof, without causing the computing device to be operated.

Attention is also directed to the fact that the blocks 70 which are relatively adjustable on the bar 69 and move with the carriage 4, constitute trips controlling the operation of the master wheel advancing mechanism of the computing device 12 and automatically cause the advance of the master wheel 59 to be inaugurated at the proper point or points in the travel of the carriage. Furthermore, the totalizer 12, in addition to its function as a grand totalizer for several parallel columns of numbers, may also be considered as a cross column totalizer inasmuch as it is capable of adding a series of numbers printed one after another in the same line instead of one under another in a column. This capability necessarily results from that re-

lation of the parts which enables a plurality of columns to be totalized, because, as is obvious, the totalizing of a cross column is simply the totalizing of a series of numbers each of which is printed in a different column position.

It is thought that from the foregoing the construction and operation of my novel calculating mechanism will be clearly apparent, but, while the illustrated embodiment of the invention is believed at this time to be preferable, I wish to be distinctly understood as reserving to myself the right to effect such changes, modifications and variations of the illustrated structure as may fall properly within the scope of the protection prayed.

What I claim is:—

1. In combination, a traveling carriage movable to a plurality of different positions or fields, a computing device, operating mechanism for the computing device, and means for causing a cooperative relation to be established between the computing device and its operating means successively as the carriage reaches different column positions during a single traverse or forward movement of the carriage.

2. In combination, a totalizer and a master wheel, a traveling carriage movable across a plurality of columns or adding fields, and means for causing a cooperative relation to be established between the totalizer and the master wheel successively as the carriage moves across successive columns or adding fields during the forward movement of the carriage.

3. The combination with a platen and printing mechanism, relatively movable to permit several columns of numbers to be printed on a work sheet, of a computing device adapted to effect a computation including the numbers in the several columns, and operating connections for the computing device, said connections being adjustable by the relative movement of the platen and printing mechanism and arranged to insure a cooperative relation between the computing device and the printing mechanism as the latter is disposed to print in different columns.

4. The combination with printing mechanism and two computing devices, one of which is designed to effect a computation embracing the computation effected by the other, and each including a series of digit carriers having differential motion, of a series of operating keys each of which is common to both computing devices, and all of which are common to each digit carrier of each device.

5. The combination with two computing devices, one of which is designed to effect a computation corresponding with a portion of a computation effected by the other, and each including a series of digit carriers, of

1. A series of operating keys common to both computing devices, means for printing digits to be included in the computations, and provision whereby any corresponding 5 digit carriers of each computing device may be operatively connected with the several keys for actuation by any one of the latter.
2. The combination with a plurality of computing devices each including a series 10 of digit carriers, of a plurality of numeral keys, digit printing mechanism, and means operated by each of the keys for actuating any two corresponding carriers of said computing devices in unison.
3. The combination with a plurality of computing devices, each including a series 15 of digit carriers, of operating means common to all of the carriers of said devices and simultaneously presentable in operative 20 relation with corresponding carriers thereof, and digit printing mechanism.
4. The combination with a platen and printing mechanism, relatively movable to 25 permit the printing of columns of numbers on a work sheet supported by the platen, of a column computing device adapted to be positioned with reference to either column, an additional computing device, and a series of operating keys each of which is 30 common to and arranged to simultaneously operate said computing devices.
5. The combination with a platen and printing mechanism, relatively movable to 35 permit the printing of a column of numbers on a work sheet supported by the platen, of a column computing device, an additional computing device, and means for operating said computing devices in correspondence and for controlling the relative movement 40 of the platen and printing mechanism.
6. The combination with printing mechanism and a plurality of separate computing devices, of keys for operating the printing mechanism and for simultaneously operating 45 said computing devices in correspondence with each other.
7. The combination with a typewriter including a platen and printing mechanism, relatively movable, and numeral keys, of 50 two computing devices one of which is adapted to effect a computation embracing a series of computations effected by the other and each including a series of digit carriers, the several numeral keys of the typewriter constituting operating means common to both 55 computing devices.
8. The combination with a typewriter including a platen, printing mechanism mounted to travel thereover, and letter and 60 numeral keys, of two computing devices, one of which is adapted to effect a computation embracing a series of computations effected by the other and each including a series of digit carriers, and provision where- 65 by corresponding digit carriers of the computing devices may be operatively connected to the numeral keys of the typewriter.
9. The combination with a typewriter including a platen, a traveling machine frame, a carriage movable on said frame, and 70 printing mechanism including letter and numeral keys movable with and controlling the movement of the carriage, of two computing devices mounted on the machine frame and each including a series of digit 75 carriers, and provision whereby corresponding digit carriers of the computing devices may be operatively connected with the numeral keys for simultaneous actuation.
10. In cooperative combination, a plurality of relatively adjustable column totalizers, actuating means therefor, and mechanism for registering the grand total of the combined operations of said totalizers.
11. The combination with the column computing devices, and the grand computing device, each including a series of digit carriers, of keys for operating the digit carriers of the column computing devices independently of the carriers of lower order, 90 printing mechanism also operated by the keys, and means for effecting the operation of the corresponding digit carrier of the grand computing device whenever a carrier of either column computing device is operated.
12. The combination with a plurality of computing devices and a grand computing device, each including a series of digit carriers, of keys constituting operating means 100 common to the carriers of the computing devices, and adapted to operate the carriers of said devices in succession, key-operated means for operating the carriers of the grand computing device in correspondence with 105 the carriers of the other computing devices, and digit printing mechanism operated by the keys.
13. The combination with a plurality of computing devices and a grand computing device, each including a series of digit carriers, of keys for simultaneously operating corresponding carriers of certain of said devices independently of the carriers of lower order, and printing mechanism operated by 115 the keys.
14. The combination with a numeral key and a printing device operated thereby, of a plurality of computing devices and a grand computing device each including a series 120 of digit carriers, and means operated by the key for actuating the carriers of either of the several computing devices and of the grand computing device in correspondence, said means being arranged to operate any 125 carrier independently of the carriers of lower order.
15. The combination with a key and a

- printing device operated thereby, of a plurality of computing devices and a grand computing device, each including a series of digit carriers, and means operated by the key for simultaneously operating a carrier of either computing device and the corresponding carrier of the grand computing device independently of the carriers of lower order. 65
10. 20. The combination with a key and a printing device operated thereby, of a plurality of column totalizers, each including a series of digit carriers, a grand computing device, means operated by the key for actuating any carrier of the column totalizers independently of the carriers of lower order, and means for actuating the grand computing device in correspondence whenever a column totalizer is operated, whereby said 70 15 grand computing device will compute the result of the combined operations of the column totalizers. 20
21. The combination with column totalizers and a grand totalizer each including a series of digit carriers and printing mechanism, of operating keys common to the printing mechanism and to the carriers of the several totalizers and arranged to operate the grand totalizer whenever either of the 75 25 column totalizers is operated. 30
22. The combination with column totalizers and a grand totalizer each including a series of digit carriers, of operating keys common to the several totalizers, operating connections between the keys and the carriers of a plurality of said totalizers to effect corresponding movement thereof, and digit printing mechanism operated by the keys. 80 35
40. 23. The combination with the column totalizers for individual columns and a grand totalizer common to several columns, of key-operated actuating means therefor, and means for repositioning the actuating means with respect to the grand totalizer after each operation of the latter embracing a complete number. 45
24. The combination with the column totalizers each including a series of digit carriers, of actuating means therefor, a traveling carriage for effecting relative movement of the column totalizers and the actuating means, to present the latter to the several digit carriers of each column totalizer, and means for registering the grand total of the combined operations of the column totalizers. 50 55
25. The combination with the column totalizers and a grand totalizer each including a series of digit carriers, of actuating means for said totalizers arranged to actuate the grand totalizer when either of the column totalizers is actuated, and a traveling carriage for shifting the relative posi- 60 65
- tions of the totalizers and the actuating means to effect the presentation of the latter to the several digit carriers of each totalizer. 70
26. The combination with the column totalizers and the grand totalizer, of a column actuator, a grand actuator, a traveling carriage for advancing the actuators with respect to the totalizers, and keys for operating the actuators. 75
27. The combination with means for printing several columns of numbers, of column totalizers for the individual columns, a grand totalizer including a series of digit carriers, and keys for operating the carriers of the grand totalizer to compute the grand total of the several columns. 80
28. The combination with printing mechanism, of a plurality of column totalizers each including a series of digit carriers, a grand computing device, keys operatively related to the printing mechanism and arranged to actuate the carriers of the column totalizers, and means for actuating the grand computing device when either of the column totalizers is actuated, whereby the grand computing device will compute the result of the combined operations of the column totalizers. 85 90
29. The combination with printing mechanism, of a plurality of computing devices and an additional computing device each including a series of digit carriers, and actuating means for the carriers of the several computing devices, said actuating means being operatively related to the printing mechanism to effect the printing of digits in succession, and said additional computing device being arranged to effect a computation including computations effected by one or more of the first named computing devices. 95 100
30. The combination with printing mechanism, of a plurality of computing devices, a grand computing device for computing the result of the combined operations of the other computing devices, and actuating keys operatively related to the printing mechanism and arranged to actuate a computing device and the grand computing device simultaneously. 105
31. The combination with a platen and printing mechanism, relatively movable in a lateral direction to permit the printing of several parallel columns of numbers on a work sheet supported by the platen, of column computing devices, a grand computing device, and operating keys common to the several computing devices. 115
32. The combination with a platen and printing mechanism, relatively movable to permit the printing of several columns of numbers on a work sheet supported by the platen, of column computing devices, a grand computing device, and keys for oper- 120 125

ating the grand computing device in correspondence with each of the column computing devices.

33. The combination with a platen and printing mechanism, relatively movable to permit the printing of several columns of numbers on a work sheet supported by the platen, of column computing devices for the individual columns, a grand computing device common to several columns, and a series of operating keys, each of which is common to all of the computing devices and arranged to simultaneously operate a plurality of said devices.

34. The combination with a platen and printing mechanism, relatively movable to permit the printing of several columns of numbers on a work sheet supported by the platen, of column computing devices for the individual columns, a grand computing device, operating keys, means for operating either of the column computing devices from said keys, and means for effecting the operation of the grand computing device in correspondence with each of the column computing devices.

35. The combination with a platen and printing mechanism, relatively movable to permit the printing of several columns of numbers on a work sheet supported by the platen, of column computing devices for the individual columns, a grand computing device, operating keys, means for operating the column computing devices in succession from said keys, and key actuated means for operating the grand computing device when either of the column computing devices is operated.

36. The combination with a platen and printing mechanism, relatively movable to permit the printing of several columns on a work sheet supported by the platen, of computing devices for the individual columns, a grand computing device, means for operating the grand computing device to effect a computation, in which the computations of the column computing devices are included, and means operated by the printing mechanism for controlling the relative movement thereof with respect to the platen.

37. The combination with a typewriting mechanism capable of printing words and several columns of numbers, of column computing devices for the individual columns, a grand computing device, and means for simultaneously operating a column computing device, the grand computing device and the typewriting mechanism.

38. The combination with printing mechanism, for printing several columns of numbers, of column computing devices for the individual columns, a grand computing device, and operating keys for simultaneously operating a column computing device, the

grand computing device and the printing mechanism.

39. The combination with a platen and printing mechanism, relatively movable to permit the printing of several columns of numbers on a work sheet supported by a platen, of column computing devices for the individual columns, a grand computing device, and operating keys each of which is arranged to operate the printing mechanism and a column computing device simultaneously, and to effect a corresponding operation of the grand computing device.

40. The combination with a platen and relatively movable printing mechanism thereover, of numeral keys for the printing mechanism, a plurality of computing devices, means for operating one of said devices upon the depression of a key of the printing mechanism, and a grand computing device for computing the result of the combined operations of the other computing devices.

41. The combination with a platen, and relatively movable printing mechanism including numeral keys, of column computing devices, a grand computing device, and means for operating the grand computing device in correspondence with each of the column computing devices.

42. The combination of a platen, and relatively movable printing mechanism including numeral keys, of column computing devices, a grand computing device, and means for simultaneously operating one of the column computing devices, the grand computing device and the printing mechanism upon the depression of a key.

43. The combination with a platen, and a carriage mounted to travel thereover, of printing mechanism including numeral keys mounted on the carriage, computing devices, means for operating one of said computing devices upon the depression of a key of the printing mechanism, and a grand computing device for computing the result of the combined operations of the other computing devices.

44. The combination with the column totalizers for individual columns and a grand totalizer common to several columns, of actuating mechanism, and printing mechanism, including numeral keys constituting operating means for the totalizer actuating mechanism and arranged to effect the actuation of the grand totalizer as numbers are printed in different columns.

45. The combination with a typewriter including a platen and printing mechanism, relatively movable, and numeral keys controlling such relative movement, of a plurality of column computing devices each adapted to effect a computation embracing the numbers in a column, and means for reg-

registering the result of the combined operations of said column computing devices.

46. The combination with a typewriter including a platen and printing mechanism, relatively movable, and numeral keys controlling such relative movement, of a plurality of column totalizers for totalizing individual columns, and a grand totalizer for computing the grand total of the several columns.

47. The combination with a typewriter including a platen and printing mechanism, relatively movable, and numeral keys controlling such relative movement, of column totalizers, means for operatively connecting the keys with the column totalizer assigned to the particular column in which the printing mechanism is disposed to print, a grand totalizer, and means whereby the numeral keys will be in operative connection with the grand totalizer whenever said keys are operatively connected to one of the column totalizers.

48. The combination with a typewriter including a platen and printing mechanism, relatively movable to permit the printing of several columns of numbers, and numeral keys controlling such relative movement, of a plurality of relatively variable column computing devices adapted to be assigned to individual columns variously located, a grand computing device adapted to effect a computation embracing the computations effected by the several column totalizers, and means for operating the several computing devices from the numeral keys.

49. The combination with a typewriting machine including a platen and printing mechanism, relatively movable to permit the printing of columns of numbers at any points on a work sheet, and numeral keys controlling such relative movement, of a plurality of column totalizers independently adjustable relative to the platen, and adapted to totalize individual columns, a grand totalizer for computing the grand total of the columns, and means for establishing a co-operative connection between any one of the column totalizers, the grand totalizer and the numeral keys.

50. The combination with a typewriter, including a platen and printing mechanism, relatively movable, and keys controlling such relative movement, of a plurality of column computing devices and a grand computing device, and means for operating said devices from certain of the keys.

51. The combination with a typewriter including a platen, traveling printing mechanism, and letter and numeral keys controlling the movement thereof in one direction, of a plurality of column computing devices independently adjustable relative to the platen and assigned to individual columns, a grand computing device adapted to effect a

computation embracing the computations effected by the column computing devices, and means whereby the numeral keys will be caused to operate any one of the column computing devices and the grand computing device.

52. The combination with a typewriter including a platen, a machine frame mounted to travel thereover, a carriage movable on the machine frame, and printing mechanism including letter and numeral keys mounted on and controlling the movement of the carriage, of a plurality of column totalizers and a grand totalizer mounted on the machine frame, and operating connections whereby the numeral keys will simultaneously operate one of the column totalizers and the grand totalizer.

53. The combination with a typewriter including a platen, a machine frame mounted to travel thereover, a carriage movable on the frame, and printing mechanism including letter and numeral keys mounted on and controlling the movement of the carriage, of a plurality of independently adjustable column totalizers carried by the machine frame and each including a series of digit carriers having differential motion, an actuator movable with the carriage and presentable to any digit carrier of any column totalizer, means for operating the actuator from the numeral keys, a grand totalizer including a series of digit carriers, and means for operating the carrier of the grand totalizer corresponding to the operated carrier of any column totalizer.

54. The combination with a column computing device and a grand computing device, each of said devices including a series of digit carriers, of a master wheel arranged to engage and operate the carriers of the column computing devices, and a grand actuator arranged to actuate the individual digit carriers of the grand computing device in correspondence with the carriers of the column computing device.

55. The combination with a plurality of computing devices and a grand computing device, each including a series of digit carriers, of an actuator presentable to the carriers of the computing devices, and a grand actuator disposed to traverse the grand computing device as the actuator traverses either of the computing devices.

56. The combination with a plurality of computing devices and a grand computing device, each including a series of digit carriers, of an actuator for the computing devices, a grand actuator for the grand computing device, means for effecting corresponding advance movements of the actuators to present them in operative relation with different digit carriers, and means for restoring the grand actuator to its initial position.

57. The combination with a plurality of computing devices and a grand computing device, each including a series of digit carriers, of an actuator for the computing devices, a grand actuator for the grand computing device, means for effecting corresponding advance movements of the actuators to present them in operative relation with different digit carriers, and automatic means for restoring the grand actuator to its initial position.
58. The combination with a plurality of computing devices and a grand computing device, each including a series of number wheels, of a master wheel, means for advancing said master wheel to successive number wheels of the computing devices, a grand master wheel arranged for advance to successive number wheels of the grand computing device, and means connecting the master wheels for corresponding rotary movement.
59. The combination with the column totalizers and the grand totalizer, each including a series of number wheels, of a column master wheel disposed for advance to successive number wheels of the column totalizers, a grand master wheel for the grand totalizer, means for advancing the master wheels in unison, and means for automatically returning the grand master wheel to its initial position after each traverse of the grand totalizer.
60. The combination with the column totalizers and the grand totalizer, each including a series of number wheels, of a column master wheel, a grand master wheel, means for causing the step-by-step traverse of each column totalizer by the column master wheel, means for causing the grand master wheel to traverse the grand totalizer in unison with the advance of the column master wheel across each column totalizer, and means for imparting corresponding rotary movements to the master wheels.
61. The combination with the column totalizers and the grand totalizer, each including a series of number wheels, of a column master wheel, a grand master wheel, means for causing the step-by-step traverse of each column totalizer by the column master wheel, means for causing the grand master wheel to traverse the grand totalizer in unison with the advance of the column master wheel across each column totalizer, means for imparting corresponding rotary movements to the master wheels, and means for automatically returning the grand master wheel to its initial position after each traverse of the grand totalizer.
62. The combination with the column totalizers and the grand totalizer, each including a series of number wheels, of a column master wheel arranged to traverse the column totalizers, a grand master wheel for the grand totalizer, means connecting the master wheels for advance in unison while the column master wheel is traversing a column totalizer, said means permitting the independent advance of the column master wheel from one column totalizer to another, and means for imparting uniform rotary movements to the master wheels.
63. The combination with the column totalizers and the grand totalizer, each including a series of number wheels, of a column master wheel arranged to traverse the column totalizers, a grand master wheel for the grand totalizer, means connecting the master wheels for advance in unison while the column master wheel is traversing a column totalizer, said means permitting the independent advance of the column master wheel from one column totalizer to another, means for imparting uniform rotary movements to the master wheels, and means for automatically returning the grand master wheel to its initial position after each traverse of the grand totalizer.
64. The combination with the column totalizers and the grand totalizer, of a column master wheel, a shaft extending therefrom, a grand master wheel slidably mounted on the shaft and rotatable therewith, and means for effecting the lateral advance of the master wheels in unison, said grand master wheel being returnable to its initial position independently of the column master wheel.
65. The combination with the column totalizers and the grand totalizer, of a column master wheel, a shaft extending therefrom, a grand master wheel slidably mounted on the shaft and rotatable therewith, means for effecting the lateral advance of the master wheels in unison, and means for automatically returning the grand master wheel to its initial position after each traverse of the grand totalizer.
66. The combination with the column totalizers and the grand totalizer, of a column master wheel, a grand master wheel, a shifting device disposed to effect the advance of the master wheels in unison while the column master wheel is traversing a column totalizer, and arranged to permit the return of the grand master wheel to its initial position after each traverse of the grand totalizer, and means for effecting such return of the grand master wheel.
67. The combination with the column totalizers and the grand totalizer, of a column master wheel, a grand master wheel, a shifter engaging the grand master wheel, a shift bar disposed for advance with the column master wheel, means for connecting the shift bar with the shifter when the column master wheel is in operative relation

with a column totalizer, and means for automatically returning the grand master wheel after each traverse of the grand totalizer.

68. The combination with the column totalizers and the grand totalizer, of a column master wheel, a grand master wheel, a swinging shifter engaging the grand master wheel, a shift bar disposed for advance with the column master wheel and having a series of projections disposed to engage the shifter when the column master wheel is brought into coincidence with a column totalizer, means for swinging the shifter out of engagement with the engaging projection when the grand master wheel completes its traverse of the grand totalizer, and means for returning the grand master wheel and shifter to their initial positions.

69. The combination with the column computing device and the grand computing device, of a column master wheel, a grand master wheel, and operating keys common to said master wheels.

70. The combination with the column adding devices and a grand adding device, of a column master wheel, a grand master wheel, means for advancing the master wheels in unison, and operating keys for said wheels.

71. The combination with the column adding devices and a grand adding device, of a column master wheel common to the several column adding devices, a grand master wheel for the grand adding device, means for advancing the master wheels in unison, and operating keys common to said wheels.

72. The combination with the column computing devices and a grand computing device, of a column master wheel, a grand master wheel, a traveling carriage for advancing the master wheels, and operating keys for the wheels.

73. The combination with the column totalizers and a grand totalizer, of a column master wheel, a grand master wheel, a traveling carriage for advancing the master wheels in unison, means for returning the grand master wheel to its initial position after each traverse of the grand totalizer, and operating keys for the master wheels.

74. The combination with the column totalizers and the grand totalizer, of keys for operating the column totalizers in succession, key operated means for operating the grand totalizer in correspondence with the operation of each column totalizer, and means for repositioning the grand totalizer operating means after each operation of the grand totalizer.

75. The combination with the column totalizer and a grand totalizer, of a column master wheel, a grand master wheel, printing mechanism including numeral keys constituting operating means common to the master wheels, and means for reposition-

ing the grand master wheel with respect to the grand totalizer after each actuation of the latter.

76. The combination with a plurality of independently adjustable column totalizers and a grand totalizer, of a column actuator, a grand actuator, and adjustable means for effecting the advance of the grand actuator as the column actuator traverses either of the column totalizers.

77. The combination with a typewriting machine including a platen and printing mechanism relatively movable, and numeral keys controlling such relative movement, of a plurality of column computing devices, a grand computing device, a plurality of actuators for said devices, and connections between one of said actuators and the numeral keys.

78. The combination with a typewriting machine including a platen and printing mechanism, relatively movable, and numeral keys controlling such relative movement, of a plurality of column computing devices, a grand computing device, a plurality of actuators for said devices, and connections between said actuators and the numeral keys.

79. The combination with a typewriting machine including a platen and printing mechanism relatively movable, and numeral keys controlling such relative movement, of a plurality of column computing devices, a grand computing device, an actuator common to the several column computing devices presentable thereto by the relative movement of the platen and printing mechanism, connections between the keys and said actuator, and a separate actuator for the grand computing device.

80. The combination with a typewriting machine including a platen and printing mechanism relatively movable, and letter and numeral keys controlling such relative movement, of a plurality of column computing devices, a grand computing device, an actuator for the column computing devices, a separate actuator for the grand computing device, and means for operatively connecting the numeral keys with said actuators.

81. The combination with a typewriting machine including a platen and printing mechanism relatively movable, and letter and numeral keys for controlling such relative movement, of a plurality of column computing devices, a grand computing device, an actuator for the column computing devices, a separate actuator for the grand computing device, and means for operatively connecting the numeral keys with said actuators to effect their simultaneous movement in corresponding degree.

82. The combination with a typewriting machine including a platen and printing mechanism relatively movable, and letter and numeral keys controlling such relative

- movement, of a plurality of column totalizers and a grand totalizer, each including a series of digit carriers, and a plurality of actuators one of which is presentable to successive carriers of the grand totalizer and independently movable to its initial position for re-presentation to said carriers. 83. The combination with a typewriting machine including a platen and printing mechanism relatively movable, and letter and numeral keys controlling such relative movement, of a plurality of column computing devices and a grand computing device each having a series of digit carriers, a plurality of actuators for the computing devices, connections between the numeral keys and the actuators, and means for automatically returning one of the actuators to its initial position after it has completed a traverse of the grand computing device. 84. The combination with a typewriting machine including a platen and printing mechanism relatively movable, and letter and numeral keys controlling such movement, of a plurality of column totalizers and a grand totalizer each comprising a series of digit carriers, a column actuator and a grand actuator both laterally shiftable by the relative movement of the platen and printing mechanism, the column actuator being thereby caused to traverse successive column totalizers and the grand actuator thus traversing the grand totalizer, and operating connections between the numeral keys and the actuators. 85. The combination with a typewriting machine including a platen and printing mechanism relatively movable, and letter and numeral keys controlling such movement, of a plurality of column totalizers and a grand totalizer each comprising a series of digit carriers, a column actuator and a grand actuator both laterally shiftable by the relative movement of the platen and printing mechanism, the column actuator being thereby caused to traverse successive column totalizers and the grand actuator thus traversing the grand totalizer, operating connections between the numeral keys and the actuators, and means for automatically returning the grand actuator to its initial position at one end of the series of digit carriers after each traverse of the grand totalizer. 86. The combination with a typewriter including a platen, traveling printing mechanism, and letter and numeral keys controlling such travel in one direction, of a plurality of column computing devices, a grand computing device, a plurality of actuators laterally shiftable with the printing mechanism, one traversing the column computing devices and the other traversing the grand computing device, and operating connections between the numeral keys and the actuators. 87. The combination with a typewriter including a platen, a machine frame mounted to travel thereover, a carriage movable on the frame, and printing mechanism including letter and numeral keys mounted on and controlling the movement of the carriage, of a plurality of column computing devices and a grand computing device mounted on the machine frame, a plurality of actuators for said devices, and operating connections between the numeral keys and the actuators. 88. The combination with a typewriter including a platen, a machine frame mounted to travel thereover, a carriage movable on the frame, and printing mechanism including letter and numeral keys mounted on and controlling the movement of the carriage, of a plurality of relatively adjustable computing devices mounted on the frame, a grand computing device, a plurality of relatively adjustable connections between the actuators and the numeral keys. 89. The combination with a computing device including number wheels, of a traveling carriage, and wheel resetting means operated through the movement of the carriage. 90. The combination with a computing device including number wheels, of wheel resetting mechanism, a traveling carriage, and means movable with the carriage to operate the resetting mechanism. 91. The combination with a computing device including number wheels, of an actuator disposed to traverse the computing device, and wheel resetting means automatically operated upon the retraction of the actuator. 92. The combination with a computing device including number wheels, a traveling carriage, wheel actuating mechanism movable by the carriage, and means for automatically resetting the computing device when the carriage is retracted. 93. The combination with a plurality of computing devices, including number wheels, of an actuator disposed for advance to successive computing devices, and means for automatically resetting the computing devices when the actuator is returned. 94. The combination with a computing device including number wheels, of a shaft for resetting the wheels, a pinion mounted on the shaft for independent movement in one direction, a rack for rotating the pinion to effect the resetting of the wheels, and means operated by the movement of the rack for restoring the shaft to its initial position. 95. The combination with a computing device including a series of number wheels, of a shaft for resetting the wheels, shaft operating mechanism including a rack and pinion for rotating the shaft to reset the wheels, and means operated by the rack for restoring the initial position of the shaft.

96. The combination with a computing device, and resetting mechanism therefor, of a traveling carriage, means mounted on the carriage for operating the resetting mechanism, and means for throwing said operating mechanism into or out of operation. 5
97. The combination with a computing device, and resetting mechanism therefor, of a traveling carriage, an actuator mounted 10 for advance by the carriage, a device mounted on the carriage to operate the resetting mechanism upon the retraction of said carriage, and means for moving said device to an inoperative position to permit 15 the retraction of the carriage without resetting the computing device. 70
98. The combination with a computing device, and resetting mechanism therefor, of a traveling carriage, an actuator mounted 20 for advance by the traveling carriage, a device mounted on said carriage for operating the resetting mechanism upon the retraction thereof, and means for preventing the actuation of the resetting mechanism by 25 said device when the carriage advances. 75
99. The combination with a computing device, and resetting mechanism therefor, of a traveling carriage, an actuator disposed for advance by the carriage, and a resetting 30 arm mounted on the carriage and disposed to operate the resetting mechanism. 80
100. The combination with column totalizers and a grand totalizer each including 35 a series of digit carriers, of actuating keys common to the carriers of the several totalizers, resetting mechanism for the column totalizers, and independent resetting mechanism for the grand totalizer. 85
101. The combination with a computing 40 device including number wheels and locking mechanism therefor, of resetting mechanism for the wheels including means operatively related to the locking mechanism to prevent the locking of the wheels at the completion 45 of the resetting operation. 90
102. The combination with a computing device, including number wheels and locking means, of wheel resetting mechanism, a traveling carriage, means operated by the 50 carriage to reset the wheels, and means for unlocking the wheels prior to the resetting thereof. 100
103. The combination with a computing device including number wheels and locking 55 mechanism therefor, of a traveling carriage, and means operated by the carriage to unlock and reset the wheels. 105
104. The combination with a computing device including number wheels and wheel 60 locking mechanism, of a traveling carriage, wheel actuating means disposed for advance by the carriage, and means for automatically unlocking and resetting the number wheels when the carriage is retracted. 110
105. The combination with a plurality of 65 computing devices including number wheels and wheel locking mechanism, of an actuator presentable to the several computing devices in succession, and means for automatically unlocking and resetting the number 70 wheels when the actuator is returned to its initial position. 115
106. The combination with a computing device including number wheels and locking mechanism therefor, of resetting mechanism 75 for the wheels, including a rotary cam operatively related to the locking mechanism to prevent the locking of the wheels when the computing device is reset. 120
107. The combination with a computing device including number wheels, and wheel locking means, of a shaft for resetting the wheels; a pinion for rotating the shaft in one direction, a cam associated with the pinion, and a lever operated by the cam to prevent the locking of the wheels when the device is reset. 125
108. The combination with a computing device including a series of number wheels, locking dogs therefor and dog retaining plungers, of a lever operatively connected to the plungers to retain them in their inactive positions, a shaft for resetting the wheels, mechanism including a rack and pinion for rotating the shaft, and a cam operated by the resetting mechanism to actuate the lever for the purpose of preventing the plungers from moving into engagement with the dogs when the wheels are reset. 90
109. The combination with a platen, a frame, a carriage movable on the frame, and printing mechanism movable with the carriage and including numeral keys, of a computing device, a trip adjustable independently of the computing device, and 100 means controlled by the trip for establishing an operative relation between the computing device and the keys when the printing mechanism is disposed to print in a given column and for automatically establishing an inoperative relation of said parts to permit digits to be printed beyond the column without operating the computing device. 105
110. The combination with a typewriter 110 including a platen, a frame, a traveling carriage, carriage propelling mechanism, and printing mechanism, of a computing device, a master wheel therefor, master wheel advancing mechanism, and automatic means 115 repeatedly connecting the master wheel advancing mechanism with the carriage propelling mechanism to repeatedly advance the master wheel across the computing devices. 120
111. The combination with a typewriter including a traveling carriage, carriage propelling mechanism, printing mechanism, and numeral keys, of a computing device having denominational members, a master actuator therefor, mechanism whereby the 125 number wheels are automatically 130

- meral keys, when operated, will move the actuator an extent corresponding to the value of the key depressed, and automatic means for connecting the master wheel with the carriage propelling mechanism at a plurality of predetermined points in the advance of the carriage whereby a limited further advance of the carriage after reaching each of said points will be accompanied by an advance of the master actuator.
112. The combination with a traveling carriage, and printing mechanism, of a computing device, a master wheel which is normally stationary relative to the computing device during the advance of the carriage, and automatic means for inaugurating the advance of the master wheel at a plurality of predetermined points in the movement of the carriage.
113. The combination with a typewriting machine including a frame, printing mechanism, and a carriage movable on the frame to permit several columns of numbers to be printed on a work sheet, of a register adapted to effect a computation embracing numbers printed in several columns, and means located at intervals and serving successively to cause an operative relation to be established between the register and the printing mechanism.
114. The combination with a typewriting machine including a frame, printing mechanism, and a carriage movable on the frame, of a computing device, and means including devices spaced at intervals on the frame to successively cause an operative relation to be established between the register and the printing mechanism.
115. The combination with a typewriting machine including a frame, printing mechanism, and a traveling carriage, of a computing device, a plurality of trips spaced at intervals on the frame, and mechanism including trip controlled means for establishing an operative relation between the printing mechanism and the computing device.
116. The combination with a typewriting machine, including a frame, a traveling carriage and printing mechanism, of a register and an actuator therefor, normally inactive mechanism for effecting the relative movement of the computing device and its actuator, to cause the presentation of the actuator to successive digit carriers of the register, and automatic means for bringing said mechanism into action at a plurality of points in a single traverse of the frame by the carriage.
117. The combination with a typewriting machine including a frame, a traveling carriage and printing mechanism, of a register, an actuator therefor, actuator advancing mechanism, and a plurality of spaced devices for causing successive operations of the actuator advancing mechanism to cause successive excursions of the actuator across the register.
118. The combination with a platen and printing mechanism, relatively movable, and keys, of a plurality of computing devices, each including a series of digit carriers, and separate actuators for operatively connecting the keys with the respective computing devices to effect the operation thereof by the keys.
119. The combination with a platen and printing mechanism, relatively movable, of a plurality of computing mechanisms adapted for use with reference to different columns, and relatively adjustable trips mounted on the frame and controlling the operations of said computing devices.
120. The combination with a platen, and printing mechanism movable thereover, of a plurality of computing mechanisms, and relatively adjustable trips controlling the operation of said mechanisms.
121. The combination with a platen and printing mechanism, relatively movable, of a plurality of computing devices, an independently adjustable trip for each computing device, and means mounted on the carriage and controlled by each trip, for establishing an operative relation between the printing mechanism and a computing device.
122. The combination with a platen and printing mechanism, relatively movable, of a computing device, a plurality of relatively variable trips, and means cooperating with the trips and controlling the establishment of an operative relation between the printing mechanism and the computing device to permit the computing device to effect a computation including numbers printed in different columns.
123. The combination with a plurality of computing devices, of independent actuators therefor, operating means common to the actuators, and separate actuator advancing mechanisms.
124. The combination with a frame, a movable carriage, and printing mechanism whereby a plurality of columns may be printed on a work sheet, of a column totalizer arranged to compute the total of a column, a grand totalizer arranged to compute the grand total of several columns, keys operatively related to the printing mechanism and arranged to actuate the column totalizer, and means for actuating the grand totalizer whenever a digit is printed in any one of the several columns to be included in the grand total.
125. The combination with typewriting mechanism movable to permit the printing of several columns of numbers, of a column computing device, and a grand computing device, means for operating the typewriting mechanism, mechanism operated by said means for operating the column

- computing device and the grand computing device, and means adjustable independently of the grand computing device to determine the location of the columns to be embraced in the computation to be effected by said grand computing device. 65
126. The combination with a frame, a movable carriage, and printing mechanism, whereby a plurality of columns may be printed on a work sheet, of a plurality of totalizers each adapted to effect a computation embracing digits printed on the work sheet, means spaced at intervals on the frame to cause an operative relation to be established between the printing mechanism and one of said computing devices when said printing mechanism is disposed to print in any one of several columns. 70
127. The combination with a frame, a movable carriage, and printing mechanism, whereby a plurality of columns may be printed on a work sheet, of a plurality of totalizers each adapted to effect a computation embracing the digits printed on the sheet, and means spaced at intervals to cause an operative relation to be established between the printing mechanism and one of said computing devices whenever said printing mechanism is disposed to print in any one of several columns. 75
128. The combination with a frame, a movable carriage, and printing mechanism, of a plurality of computing devices and a plurality of trips, one of said trips controlling the operation of one computing device, and a plurality of said trips controlling the operation of another computing device. 80
129. The combination with a frame, a movable carriage, and printing mechanism mounted on the carriage and including keys, of a plurality of computing devices, a plurality of trips mounted on the frame, and trip controlled means for rendering the computing devices operative by the keys. 85
130. The combination with a platen and printing mechanism, relatively movable, and keys, of a totalizer, a plurality of trips, and mechanism controlled by the trips for rendering the totalizer operative by the keys. 90
131. The combination with a typewriter including a frame, printing mechanism, and a movable carriage, of a plurality of registers, a plurality of other devices, and means controlled by said last named devices for causing a cooperative relation to be established between the printing mechanism and a register. 95
132. The combination with a frame, a movable carriage, and printing mechanism, of a plurality of registers, operating mechanism therefor, and a plurality of trips controlling the operation of one of said registers. 100
133. The combination with two primary elements, to-wit, paper supporting means and printing mechanism, one of said elements being relatively stationary and the other movable to permit several columns of numbers to be printed on a work sheet, of a computing device common to several columns, and means carried by the relatively stationary element to predetermine the location of several columns to be served by the computing device. 105
134. The combination with two primary elements, to-wit, paper supporting means and printing mechanism, one of said elements being relatively stationary and the other movable to permit several columns of numbers to be printed on a work sheet, of a computing device and an actuator relatively movable, but normally relatively stationary, said computing device being common to the several columns, means carried by one of the primary elements for causing an operative connection to be automatically established between the printing mechanism and the computing device at a predetermined point in the relative movement of the two primary elements, and means carried by the other primary element to cause the relative movement of the computing device and its actuator at the proper time. 110
135. The combination with two primary elements, to-wit, a platen and printing mechanism, one of said elements being relatively stationary and the other movable, a computing device having denominational members, a master actuator therefor, said computing device and actuator being relatively movable to present the actuator in cooperative relation with successive denominational members, an adjustable trip associated with one of the primary elements to cause an operative relation to be established between the actuator and the printing mechanism at the proper point in the relative movement of the primary elements, and an adjustable trip associated with the other primary element to cause the advance of the actuator to successive denominational members at the proper time. 115
136. The combination with two primary elements, to-wit, paper supporting means and printing mechanism, relatively movable, a computing device, an actuator therefor, and two sets of trips, one set controlling the operative connection between the printing mechanism and the actuator, and the other set controlling the movement of the actuator across the computing device. 120
137. The combination with a typewriting machine including printing mechanism, a frame, and a traveling carriage, of a computing device, a plurality of trips mounted on the frame, a trigger mounted on the carriage and disposed to be operated by the trips, and means controlled by the trigger 125

for establishing an operative relation between the computing device and the printing mechanism.

138. The combination with a stationary platen and movable printing mechanism, of a plurality of computing devices, a plurality of trips, and trip controlled mechanism for operatively connecting the printing mechanism with either computing device.

139. The combination with a plurality of computing devices and a traveling series of keys, of trip controlled means for operatively connecting the keys with the respective computing devices.

140. In a key operated calculating machine, a plurality of receiving mechanisms each embodying ten carrying mechanism, in combination with a plurality of setting wheels all operable from the same set of figure keys and adapted to operate the different receiving mechanisms simultaneously, in columns having the same place value.

141. In a key operated calculating machine, two receiving mechanisms each embodying ten carrying mechanism, in combination with two setting wheels operable from the same set of figure keys and adapted to operate the two receiving mechanisms simultaneously, in two different columns each having the same place value.

142. In a calculating machine, the combination of a main setting wheel, an auxiliary setting wheel and a plurality of receiving mechanisms, each adapted to be operated by one of said setting wheels while the other receiving mechanism is being operated by the other.

143. The combination with a typewriter including a platen and printing mechanism, relatively movable, and numeral keys controlling such relative movement, a grand totalizer including a series of denominational members and carrying means, and automatic means whereby, when the printing

mechanism is operated, to print a number in any one of a plurality of laterally spaced columns, the grand totalizer will be under the control of the keys and compute the grand total of the numbers printed in the several columns.

144. The combination with a computing device including a series of denominational members, of operating means for the computing device, a carriage mounted to travel forward and back, mechanism controlled by the movement of the carriage and operated to bring the computing device and its operating means into cooperative relation during a plurality of periods in the forward movement of the carriage and to establish, during each period, a cooperative relation between the operating means and successive denominational members of the computing device.

145. The combination with a computing

device and a master actuator, of two opposed springs tending to effect relative movement of the computing device and actuator in opposite directions and means whereby said springs are rendered alternately effective.

146. The combination with two computing devices each including a series of digit carriers, of a series of keys, each of which is common to both computing devices, and all of which are common to each digit carrier of each device, and means whereby the depression of any one of said keys will result in the operation of a digit carrier of each computing device.

147. The combination with column totalizers, each including a series of digit carriers, of actuating mechanism therefor, a traveling carriage arranged to cause the actuating means to become effective to operate successive digit carriers of the column totalizers, and means for registering the grand total of the combined operations of the column totalizers.

148. In a calculating machine, the combination of two receiving mechanisms, each embodying ten carrying mechanisms, and two setting members, one for each receiving mechanism, said setting members being adapted to operate said receiving mechanisms simultaneously in the same decimal columns of the respective receiving mechanisms.

149. In combination with a traveling carriage, a computing device, keys controlling the operation of the computing device, and means for causing the computing device to be brought under the control of the keys by the movement of the carriage to successive column positions.

150. The combination with a plurality of computing devices each including a series of digit carriers, of a plurality of keys, digit printing members operable one after another by the keys, and means operated by each of the keys for actuating any two corresponding carriers of said computing devices.

151. The combination with a plurality of computing devices, each including a series of digit carriers, of operating means common to all of the carriers of said devices, and simultaneously presentable in operative relation with corresponding carriers thereof, and digit printing members operable to print one at a time the digits to be embraced in the computation and cooperatively related to said operating means.

152. The combination with a plurality of computing devices, each including a series of digit carriers, of operating means including keys common to all of the carriers of said devices and simultaneously presentable in operative relation with corresponding carriers thereof, and digit printing

members operable as the keys are depressed, to print, one after another, the digits included in the computation.

153. The combination with a platen and printing mechanism, relatively movable to permit the printing of columns of numbers on a work sheet supported by the platen, of a column computing device adapted to be positioned with reference to either

10 column, an additional computing device, and a series of operating keys, each of which is common to and arranged to simultaneously operate said computing devices and the printing mechanism.

154. The combination with a platen and printing mechanism, relatively movable to permit the printing of columns of numbers on a work sheet supported by the platen, of a column computing device adapted to be positioned with reference to either column, an additional computing device, a series of operating keys, and two master wheels, one for each computing device, both of said master wheels and the printing mechanism being simultaneously operable upon the depression of a key to print a digit and to operate both computing devices.

155. In a machine of the character described, the combination of a typewriting machine having a carriage, adding mechanism comprising denomination selecting mechanism, and means for connecting said typewriter carriage with said selecting mechanism comprising one or more parts that move with said carriage, a coupler connected with said selecting mechanism and arranged to be operated by said part as the carriage moves through the adding column, means operated by the motion of said carriage, for disconnecting said coupler from said part at the end of the adding column, and means for restoring said coupler to normal position when so disconnected.

156. In a machine of the character described, the combination of a typewriting machine having a carriage, adding mechanism comprising denomination selecting mechanism, and means for connecting said typewriter carriage with said selecting mechanism comprising a part that moves with said carriage, a coupler connected with said selecting mechanism and arranged to be operated by said part as the carriage moves

15 through the adding column, and means operated by the motion of said carriage for moving said coupler out of the path of said part at the end of the adding column and for restoring said coupler to normal position,

60 whereby said carriage can move through an adding column without being arrested by said coupler.

157. The combination with the column

carriers, of keys for operating the digit carriers of the column computing devices independently of the carriers of lower order, and means for effecting the operation of the corresponding digit carriers of the 70 grand computing device whenever a carrier of either column computing device is operated.

158. The combination with column totalizers and a grand totalizer each including a 75 series of digit carriers, of operating keys common to the carriers of the several totalizers, and arranged to operate the grand totalizer whenever either of the column to

talizers is operated.

159. In a machine of the character described, the combination of a typewriting machine having a carriage, adding mechanism comprising denomination selecting mechanism, and means for connecting said typewriter carriage with said selecting mechanism comprising a part that moves with said carriage, a coupler connected with said selecting mechanism and arranged to be operated by said part as the carriage moves through the adding column, and a stationary cam for moving said coupler out of the path of said part at the end of the adding column.

160. The combination with a typewriting machine including a traveling carriage, numeral keys and printing mechanism, of two computing devices, each including a series of digit carriers, and connections whereby the operation of the keys to print numbers included in a computation will cause the operation of the two computing devices, one of which will effect a computation embracing the computation effected by the other.

161. The combination with a typewriting machine including a carriage, numeral keys and printing mechanism, of two computing devices one of which effects a computation corresponding with a portion of the computation effected by the other, and each computing device including a series of digit carriers, and means whereby a series of the typewriter keys will be common to both computing devices to cause the operation of corresponding digit carriers of each computing device upon the depression of one of the keys to print a digit.

162. The combination with a typewriting machine including a carriage, numeral keys and printing mechanism of a plurality of receiving mechanisms, each having a plurality of wheels occupying different denominational positions, a plurality of master

wheels for simultaneously operating corresponding wheels of the respective computing devices and having their denominational re-

125 position to the computing determined by the position of the typewriter carriage, and means whereby the setting wheels will be

130

caused to operate the computing devices upon the operation of a key of the typewriter to print a digit.

163. The combination with a platen and printing mechanism relatively movable to different column positions or adding fields, a series of keys, a computing device and means whereby said computing device will be automatically and successively brought under the control of the keys during the relative movement of the platen and printing mechanism to successive column positions.

164. The combination with paper supporting means and printing mechanism relatively movable to permit several columns of numbers to be printed on a work sheet, of a computing device common to the several columns, means whereby the computing device will be operatively connected with the

printing mechanism whenever the printing mechanism is disposed to print in any one of the several columns, and keys constituting actuating means for the printing mechanism and computing device.

165. In a calculating machine, the combination of a plurality of receiving mechanisms, each embodying ten carrying mechanism and a plurality of setting wheels for operating said receiving mechanisms simultaneously in the same decimal columns of the respective receiving mechanisms.

166. The combination with a computing device and means including keys for operating the same repeatedly in the same denominational positions and means acting as an incident of such operation to automatically effect relative denominational repositioning of the computing device and its operating means.

167. The combination with a computing device and actuating means therefor having relative denominational movement forward and backward, and means serving incidental to such relative movement in one direction to automatically reverse the direction of relative movement and thus reposition the parts for a repetition of the operation.

168. The combination with a computing device common to several columns, of key controlled actuating means therefor, and means serving incidental to the operation of said actuating means to effect denominational repositioning thereof after each operation embracing a complete number.

169. The combination with a computing device, of means including keys for causing successive operations of the computing device, and means controlled by said keys and serving to automatically effect denominational repositioning of the keys and computing device.

170. The combination with a platen and printing mechanism relatively movable to permit several columns of numbers to be printed on a work sheet, of a computing de-

vice and operating connections therefor, means for determining both the denominational and columnar relation of the platen, printing mechanism, computing device and operating connections, by the relative movement of the platen and printing mechanism.

171. The combination with a platen and printing mechanism relatively movable to permit several numbers to be printed on a work sheet, in different laterally spaced column positions, of a computing device and operating means therefor, relatively movable in opposite directions for denomination spacing and repositioning, and means serving incidental to the relative movement of the platen and printing mechanism beyond a column position to reposition the computing device and its operating means for another operation.

172. The combination with a computing device including a series of number wheels, of a master wheel, means for imparting relative lateral movement to the computing device and master wheel to change their denominational relation and separate means controlled by said first named means for imparting relative movement to the computing device and master wheel to change their column relation.

173. The combination with a computing device including a series of denominational members, of a master wheel, means for effecting relative movement of the computing device and master wheel to change their denominational relation, and means controlled by said first named means for effecting relative movement of the computing device and its master wheel to reposition the same automatically when a given denominational position is reached.

174. The combination with a computing device and operating means therefor, relatively movable laterally in opposite directions to change their denominational relation and to reposition the parts for successive operations, of a traveling carriage movable in a single direction to control the relative movement of the computing device and its operating means in both directions.

175. The combination with a typewriter including a carriage, keys and printing mechanism, of a computing device and operating means therefor, including keys of the typewriter, means serving to effect relative denominational movement of the computing device and its operating means as said keys are operated, and a motor for effecting relative retractile movement of the computing device and its operating means.

176. The combination of a computing device and its master wheel, a mechanism whereby said device and wheel will be relatively shifted to change their denominational relation and automatically reshifted the instant the limit of denominational

movement is reached to enable successive operations of the same character.

177. The combination with a platen and printing mechanism relatively movable to permit numbers to be printed side by side in different column positions, of a computing device operated by the printing mechanism as the numbers are printed to effect a computation embracing the numbers so printed, the said operation of the computing device occurring incidental to the printing of the numbers.

178. The combination with a typewriter including a platen and printing mechanism relatively movable and numeral keys, of a computing device and means whereby the operation of the keys to print numbers side by side in different column positions and including digits in the same denominational positions, will automatically result in the operation of the computing device to effect a computation including said numbers.

179. The combination with a typewriter including a carriage, keys and printing mechanism, of a computing device and means whereby the advance of the carriage to successive column positions or fields will cause the computing device to come successively under the control of the typewriter keys.

180. The combination with a typewriter including a carriage, keys and printing mechanism, said carriage being movable as usual to permit the printing of numbers in different laterally spaced column positions, of a computing device common to a plurality of column positions to effect a computation embracing numbers printed in said column positions, an actuating means for the computing device, said actuating means and the computing device having relative back and forth movement to change their denominational relation as numbers are printed and to restore their relation for the next operation, and means whereby the relative forward movement of the computing device and its operating means will be inaugurated by the movement of the carriage into position for the printing of a number in a column position, and whereby the relative return or backward movement of the computing device and its operating means will be consequent upon the movement of the carriage beyond such column position.

181. The combination with a computing device including a series of denominational members and carrying means, of a master wheel, and separate means, each automatically controlled, for effecting relative lateral movement of the computing device and its master wheel in opposite directions to permit repeated operations of the computing device, each operation involving successive number wheels.

182. In combination, a traveling carriage

movable to a plurality of different column positions or fields, a computing device, operating mechanism for the computing device, and means dependent upon the movement of said carriage for causing a co-operative relation to be established between the totalizer and its operating means successively as the carriage reaches different column positions during a single traverse or forward movement of the carriage.

183. The combination with paper-supporting means and printing mechanism, relatively movable to permit several columns of numbers to be printed on a work sheet, of a computing device common to the several columns, means called into operation by reason of the relative movement between said paper-supporting means and said printing mechanism, for operatively connecting the computing device with the printing mechanism whenever the printing mechanism is disposed to print in any one of the several columns, and keys constituting actuating means for the printing mechanism and computing device.

184. The combination with a platen and printing mechanism, of means for effecting the relative step-by-step movement thereof to permit the printing of several columns on a work sheet, a computing device, and means dependent upon the manipulation of the printing mechanism to print numbers in the several columns, for operating said computing device to effect a computation including the numbers printed in the several columns.

185. The combination with printing mechanism and a platen for the support of the work sheet, said platen and printing mechanism being relatively movable to permit the printing of several columns of numbers on the work sheet, a computing device, and means for operating said computing device, as numbers are printed in the different columns, to compute a result with such numbers included in the computation, said means also controlling both the relative movement of platen and printing mechanism, and the adjustment of the computing device required for computing together the numbers that are printed in the different columns.

186. The combination with a typewriter including a platen and printing mechanism, relatively movable to permit the printing of columns at different points on a work sheet backed by the platen, and keys, of a computing device, and means for operating the same to effect a computation embracing the numbers in several columns, said operating means including means for automatically controlling the computing device in a manner to cause the numbers in the different columns to be computed together.

187. The combination with a computing device including a series of denominational

members, of operating means for the computing device, a carriage mounted to travel forward and back, and mechanism dependent upon the travel of said carriage and 5 operating to bring the computing device and its operating means into cooperative relation during a plurality of periods in the forward movement of the carriage and to establish, during each period, a cooperative 10 relation between the operating means and successive denominational members of the computing device.

188. The combination with a computing device including a series of denominational 15 members and carrying means, of a master wheel, means for effecting relative movement of the computing device and master wheel to change their denominational relation, and automatic means for effecting relative movement of the computing device and its master wheel to reposition the same mechanically.

189. In a calculating machine, the combination with actuating devices, of two independently operable groups of totalizer 25 wheels in operative relation to said actuating devices, and means for effecting a relative lateral shifting movement between one of said groups and its actuating device independently of the other group and actuating 30 device; said groups being simultaneously operable by said actuating devices, one of said groups being operable by its actuating device either simultaneously with or independently of the other group and actuating 35 device.

190. In a calculating machine, the combination with groups of totalizer wheels, of actuating means therefor, means for effecting 40 relative shifting movement between said groups and said actuating means so as to enable said actuating means to cooperate with a selected group of totalizer wheels, and additional group of totalizer wheels, 45 and actuating means normally in operative relation to said additional group, whereby numbers registered in any of the first-mentioned groups may be accumulated in the last-mentioned group of totalizer wheels.

191. In a calculating machine, the combination with a group of totalizer wheels, and actuating means individual to said group, of a plurality of groups of totalizer wheels, and actuating means operable upon either 55 one or the other of the groups of said plurality, and cooperatively related to the actuating means first named.

192. In a calculating machine, the combination with groups of totalizer wheels, and 60 actuating means for said groups, of means for effecting relative shifting movement between said groups and said actuating means to enable a selected group to be operated by said actuating means, an additional group 65 of totalizer wheels, and additional actuating

means individual to said additional group and normally in operative relation thereto, and cooperatively related to the first named actuating means.

193. In a calculating machine, the combination with groups of totalizer wheels, and actuating means for said groups, of means for effecting relative shifting movement between said groups and said actuating means to enable a selected group to be operated by 70 said actuating means, an additional group of totalizer wheels, additional actuating means individual to said additional group and normally in operative relation thereto, and means under the control of the operator for 80 effecting cooperation between any group in said plurality with the first-mentioned actuating means to permit conjoint action of two groups of totalizer wheels.

194. In a calculating machine, the combination with actuating devices, of two independently operable groups of totalizer wheels, and means for effecting a relative lateral shifting movement between one of 85 said groups and its actuating means independently of the other group and actuating means.

195. In a calculating machine, the combination with a laterally movable carriage, of groups of totalizer wheels, actuating devices 95 for said groups, one of said groups constantly in operative relation to its actuating device, and means under the control of said laterally movable carriage for effecting relative shifting movement between another of 100 said groups and its actuating means.

196. In a calculating machine, the combination with two groups of totalizer wheels and actuating devices therefor, of printing 105 means operable to print numbers and to operate said actuating devices as said numbers are printed.

197. In a calculating machine, the combination with two groups of totalizer wheels and separate actuators therefor, means being provided for effecting relative lateral displacement between one of said groups and its actuator, printing types, and means associated with said actuators for causing said 110 printing types to print.

198. In a calculating machine, the combination with printing mechanism, including a laterally shiftable carriage, of groups of totalizer wheels, actuators for said totalizers, means connected to said carriage for effecting relative shifting movements between the totalizers and the actuators, printing types associated with the actuators to be controlled simultaneously therewith, and means associated with said carriage for causing the 120 types to make printing impressions of the items in separate columns on the work sheet, which items are introduced into the different groups of totalizers.

199. In a calculating machine, the combi- 130

nation with supporting means for a work sheet, of a laterally movable carriage, groups of totalizer wheels, actuators therefor, means connected to said carriage for effecting relative shift between the groups of totalizer wheels and the actuators, printing types connected to be operated simultaneously with the actuators in introducing items into said groups of totalizer wheels, and means whereby the laterally shiftable carriage will effect a cooperation between the actuators and selected groups of totalizer wheels, whereby separate columns of numbers may be registered in said groups of totalizer wheels, and on said work sheet, the said columns being individually totalized.

200. In a calculating machine, the combination with a laterally shiftable carriage, of a paper support to cooperate with said carriage to position a sheet with respect to the printing point, groups of totalizer wheels, actuating means to cooperate with the groups of totalizer wheels, means connected to said carriage for effecting relative shifting movement between the groups and the actuating means, printing types controlled simultaneously with the actuating means whereby items registered in said groups of totalizer wheels may be printed in parallel columns on a sheet and separately totalized in said groups of totalizer wheels, and another group of totalizer wheels with actuating means therefor, in which group items or totals introduced into any of the first-mentioned groups of totalizers may be registered.

201. In a machine of the class described, the combination with alphabetical printing mechanism including a platen, of types for recording numbers, total wheels operable to add the numbers so recorded, means for producing and retaining within the total wheels separate totals of the distinct items so recorded, and automatic means for producing a grand total in addition to the said separate totals.

202. In a calculating machine, the combination with a laterally movable carriage, of groups of totalizer wheels, actuating means therefor, said actuating means and said groups being relatively shiftable, and means independently movable with respect to the carriage for effecting a relative shifting movement between a group of totalizer wheels and the actuating means, said shifting means being under the control of said carriage when the latter is moving in one direction.

203. The combination of a computing device, a denomination selector therefor, a carriage, a coupler for advancing the selector, a plurality of shifters movable with the carriage to connect the coupler therewith repeatedly, means for withdrawing the coupler from the shifters at a definite point in

its advance with each shifter, and means whereby the shifters can freely return past the coupler when the carriage returns.

204. The combination with a traveling typewriter carriage, of lugs connected at intervals to the said traveling carriage, computing mechanism including a traveling member, a catch connected to said traveling member and adapted to engage said lugs to enable the typewriter carriage to advance said traveling member step-by-step, an inter- 75 ceptor adapted to trip or disconnect said catch from each of said lugs, so as to be engaged by the succeeding lug; and a spring adapted to retract said traveling member.

205. In a combined typewriting and computing machine, the combination with a traveling carriage and a bar connected thereto, of lugs settable along said bar, a hook normally lying in the path of said lugs, a guide for said hook as it is drawn along by said lugs, a cam for positively moving said hook out of the path of its lugs at one end of its movement, and computing mechanism comprising a denomination-selecting device connected to said hook. 80 85 90

206. The combination with a typewriting mechanism having a printing point and including a traveling carriage, of a computing mechanism including a traveling element, and means carried by the carriage for repeatedly bringing the traveling element of the computing mechanism to positions corresponding to the printing point during a single excursion of the carriage so that the denominations of the numbers computed will accord with the denominational columns of the numbers as written by the typewriting mechanism in the several computing zones or columns. 100

207. The combination with a typewriter carriage, of shifting devices carried upon said carriage, a computing mechanism having a traveling element, connections between said traveling element and said devices whereby the position of the traveling element is controlled by the shifting devices, and means dependent upon the position of said typewriter carriage for interrupting the connection between the shifting devices and the traveling computing element. 105 110 115

208. The combination of a carriage, computing mechanism, an actuator therefor, both normally stationary, and means repeatedly actuated by the movement of the carriage in a uniform direction for causing motion of one of said elements, the actuator and computing mechanism, relatively to the other, at variable points in the movement of the carriage. 120

209. In an apparatus of the character described, the combination of main and secondary computing mechanisms, each comprising computing devices, an actuator for each com-

- puting mechanism, means for operating said actuators in unison, means for producing a relative advance of the main actuator to engage in succession its computing devices, and 5 means for producing a plurality of relative advances of the secondary actuator to engage its computing devices during one complete advance of the main actuator.
210. The combination of a typewriter carriage, computing mechanism, an actuator therefor, a device movable by the typewriter carriage, a plurality of means adjustably carried by said device for connecting said actuator thereto, and a single means, independent of the former means, for disconnecting it therefrom.
211. The combination with a platen and printing mechanism relatively movable, calculating mechanism comprising two elements, computing mechanism and an actuator therefor, one of which is movable relative to the other in one direction, means for moving said element in a reverse direction, and means variably located for arresting the 25 reverse movement.
212. In an apparatus of the character described, the combination of main and secondary computing mechanisms, each comprising a continuous series of computing devices, an actuator for each computing mechanism, means for operating said actuators in unison, means for producing a relative advance of the main actuator to engage in succession its computing devices, and means for successively connecting the secondary actuator with the main actuator to cause them to advance in unison the distances through which the main actuator has advanced when such connections are successively made, being 40 variable.
213. In an apparatus of the character described, the combination of main and secondary computing mechanisms, each comprising a continuous series of computing devices, an actuator for each computing mechanism, means for operating said actuators in unison, means for producing a relative advance of the main actuator to engage in succession its computing devices, means for successively connecting the secondary actuator with the main actuator to cause them to advance in unison the distances through which the main actuator has advanced when such connections are successively made being variable, and means for automatically causing the return of the secondary actuator when it has completed its advance.
214. The combination of a typewriter carriage, stationary computing mechanism, an actuator therefor, movable with the typewriter carriage, means for disconnecting said actuator from the carriage, means for moving the actuator in the reverse direction, and means for varying the extent of said reverse 65 movement.
215. The combination of a typewriter carriage, calculating mechanism comprising two primary elements, a computing device and an actuator therefor, means for advancing one of said elements relatively to the other, means for operatively connecting said advancing means with the typewriter carriage, whereby they move in unison, means for breaking said connection at a constant point in said advance, means for moving said element in the reverse direction when said connection is so broken, and means for varying the extent of said return movement. 70
216. The combination of a typewriter carriage, calculating mechanism comprising two elements, to wit, computing mechanism and an actuator therefor, said elements having a relative forward and reverse movement, means selectively located at predetermined points corresponding to writing spaces for 85 arresting the relative reverse movement of said elements and for causing the forward movement thereof with the carriage.
217. The combination of a typewriter carriage, stationary computing mechanism, an actuator therefor, a device movable by the typewriter carriage, means selectively located at predetermined writing spaces of the typewriter for arresting a reverse movement of said actuator, and for causing a forward movement thereof with the carriage, means for disconnecting said latter movement, and means for effecting the reverse movement. 90
218. In a combined typewriting and computing machine, the combination with a letter-feeding typewriter carriage, of a main computing mechanism including an element connected to the typewriter carriage to travel therewith, and a cross computing mechanism including an element connected to said main traveling element to travel therewith intermittently during each run of the typewriter carriage. 100
219. In a combined typewriting and computing machine, the combination of a typewriter carriage, a computing device, a hook connected to said computing device, a bar on the typewriter carriage, lugs settable along said bar and engageable by said hook, and means for automatically and intermittently releasing said hook from said lugs. 110
220. In a combined typewriting and computing machine, the combination of a typewriter carriage with a bar on the carriage, of stops settable on said bar, lugs on said stops, a latch or hook, a spring normally urging said hook into the path of said lugs, a cam adapted to engage said hook at one end of its travel to positively move it out of the path of said lugs, and a spring normally returning said hook. 120
221. The combination with a plurality of computing heads, of master wheels for said heads, means for driving said master wheels from a single source, and means for giving 130

a step-by-step movement to said master wheels in the same direction, one of said master wheels being independently retractible.

222. The combination with a typewriter carriage, of means connected thereto and including lugs, a hook or coupler, means to cause the hook to engage the lugs in succession, means dependent upon the movement of the carriage to release the coupler from the lugs, and computing mechanism including a part connected to said hook and having a denomination determining movement.

223. In a combined typewriting and computing machine, the combination with traveling lugs, of a coupler or hook, a spring normally urging said hook into the path of said lugs, a cam adapted to engage said hook at one end of its travel to positively move it out of the path of said lugs, a spring normally returning said hook, and computing mechanism comprising a denomination determining part connected to said hook.

224. In a combined typewriting and adding machine, the combination with a carriage and printing instrumentalities of a typewriter, of a series of lugs connected to the carriage, mechanism for adding numbers written on said typewriter, said adding mechanism including a denomination determining part that moves step-by-step in unison with the motion of said typewriter carriage, and means for connecting said denomination determining part with one of said lugs when said carriage reaches an adding zone, for releasing said denomination determining part and restoring it to normal position when the carriage passes out of the adding zone, and for connecting said denomination determining part with another lug when the carriage reaches another adding zone, whereby numbers written on one line of writing can be added together.

225. The combination with primary mechanism for adding numbers written in each of a plurality of primary columns, so as to produce the footing (or total) of each individual column separately from the others, of secondary mechanism for simultaneously computing the gross amounts (or cross footing) of all the numbers written in the several columns respectively on each line across the page, and automatically computing the sum of all such gross amounts or cross footings, a primary master wheel actuating said primary mechanism, a gross master wheel actuating said secondary mechanism, said secondary mechanism including gross computing wheels, said primary mechanism including primary computing wheels, all of said computing wheels being arranged in column groups, and means for effecting repeated relative reciprocations between the said gross master wheel and the said gross computing wheels during a single complete relative movement

or progress in one direction between the single primary master wheel and all of the several column groups of primary computing wheels.

226. The combination with a plurality of computing mechanisms, each having a series of computing wheels, and adjustable connections enabling, at will, the bringing of the action of the computing wheels of one computing mechanism in synchronism with the action of any of the computing wheels of another computing mechanism.

227. In a calculating machine, a plurality of groups of total wheels, means for operating said groups of wheels simultaneously or separately as described, and means for recording the total in one group and simultaneously introducing that total into another group of total wheels.

228. In a calculating machine, the combination with two groups of totalizer wheels, of means under the control of the operator for consecutively registering items in either group, a third group of totalizer wheels, and means for causing items accumulated in one of the first named groups to be accumulated in the third group.

229. In a calculating machine, the combination with actuating devices, of two independently operable groups of totalizer wheels in operative relation to said actuating devices, and means for effecting a relative lateral shifting movement between one of said groups and its actuating device independently of the other group and actuating device, said groups being simultaneously operable by said actuating devices.

230. The combination with a typewriter including a carriage, keys and printing mechanism, of computing mechanism including two parts relatively movable for denominational spacing, means whereby the advance movement of the carriage to given denominational positions of different columns to begin the printing of numbers therein will result in a like denominational relation of the parts of the computing mechanism.

231. The combination with a typewriter including a carriage, keys and printing mechanism, of computing mechanism including two parts relatively movable for denominational spacing, means whereby the advance movement of the carriage to given denominational positions of different columns to begin the printing of numbers therein will result in a like denominational relation of the parts of the computing mechanism, and said parts of the computing mechanism being restorable to their normal denominational relation independently of the retraction of the carriage.

232. The combination with a typewriter including a carriage, keys and printing mechanism of a computing device and its

actuator, one of which is a relatively movable element, and a series of devices brought into action by the operation of the type-writer keys to determine the relative de-
5 nominational position of the computing de-
vice and its actuator at the beginning of its operations.

233. The combination with a carriage and computing mechanism, including a denominational selector, of means including a coupling member and a series of lugs, for
10

connecting said selector and the carriage at predetermined intervals in the travel of said carriage.

In testimony that I claim the foregoing as my own, I have hereto affixed my signature 15 in the presence of two witnesses.

HIRAM JOSEPH HALLE.
